Filed Apr. 7, 1960, Ser. No. 20,712

14 Claims. (Cl. 187—29)

This invention relates to elevator systems and it has particular relation to elevator systems wherein operation is automatically modified to provide different modes of operation.

It is well known that modern elevator systems must have sufficient flexibility to handle various traffic conditions. For example, during a substantial part of the business day the demand for elevator service in the two directions of travel generally is substantially balanced. Such periods are known as "off-peak" periods.

In an office building, an elevator system may be called upon to handle traffic conditions which occur during peak periods wherein large numbers of passengers desire to travel in one direction at substantially the same time. Such a traffic condition may occur, for instance, at the close of a business day during a "down-peak" period when large numbers of elevator passengers desire to proceed downwardly from the higher floors at approximately the same time. During a down-peak period the elevator cars tend to become fully loaded at the higher floors of the building. Under such circumstances, passengers awaiting service at the lower floors of the building may be kept waiting for unduly long periods of time. Among the solutions proposed for this problem is that taught by the Santini et al. Patent 2,840,189, in which an elevator car under certain conditions is assigned to serve specified floors. Another solution involves the division of the floors of a building into zones with one or more elevator cars assigned to provide service primarily for each of the zones. Such operation is well known in the art and has proven to be of material assistance in solving the problems of providing adequate service during peak periods.

In some heavily populated buildings it has been found desirable to stagger the hours in order to depopulate one floor at a time in a predetermined sequence. Such staggered depopulation may occur, for example, during the lunch period. Furthermore, floors for which staggered depopulation is necessary may be the upper floors of the building. The passengers from these floors, in accordance with the predetermined sequence, may desire transportation to a lower floor on which is located a lounge, to another lower floor on which is located a cafeteria or to the lower terminal or street level floor. In order to meet the requirements of such traffic conditions, the teachings of the above-mentioned Santini et al. patent and zoned down-peak operation may not be the best solutions.

In accordance with the invention, a structure wherein it is desired to depopulate floors in a predetermined sequence is provided with an elevator system having means for conditioning the system to furnish special service during such depopulating periods. Although aspects of the invention are applicable to elevator systems employing only a single car, the invention is particularly suitable for systems employing a plurality of elevator cars and will be discussed with reference to a multiple-car elevator system. For purposes of illustration, it will be assumed that during off-peak periods the elevator system is conditioned to operate each elevator car on through trips between terminal floors or landings. Although suitable dispatchers may be provided for dispatching the elevator cars at predetermined intervals from the terminal floors during off-peak operation, such dispatch-

2

ers are not shown in the illustrated embodiment of the invention in order to simplify the presentation thereof.

During special service operation, successive predetermined groups of elevator cars in the system are assigned to serve successive predetermined floors of the structure for depopulating such floors. In a preferred embodiment of the invention, each group of cars is assigned to a given floor for a predetermined assigned period of time. The number of cars in each group and the predetermined time during which each group of cars serves its assigned floor is based on unloading such floor in a minimum number of trips by its assigned cars. This, in turn, depends upon the potential load at the associated assigned floor. In addition, each group of cars is conditioned to provide service from its assigned floor in only a predetermined direction, for example, the down direction of car travel.

Each assigned elevator car is conditioned to by-pass all up and down corridor calls for elevator service. Furthermore, each assigned car may be conditioned to respond to car calls for only predetermined floors and to ignore car calls for the remainder of the floors. For example, during special service operation an assigned car may answer car calls for the floor on which the cafeteria is located and for the lower terminal floor.

During special service operation, elevator cars which are not assigned to predetermined floors may remain on off-peak operation, that is, each unassigned car may provide balanced service for all unassigned floors by responding to all corridor calls and to car calls for such floors. Desirably, at least one elevator car in the bank remains conditioned for off-peak operation during each period of special service operation.

Assuming that it is desired to provide special service operation for an assigned floor in the down direction, an assigned car which is traveling in the up direction toward its assigned floor will stop at such floor and will be conditioned for subsequent travel in the down direction. Concurrently, the doors of the assigned car will open to permit loading of the car. The assigned car will remain at its assigned floor until it is loaded or until the lapse of a predetermined time, whichever occurs first. The car then will leave the assigned floor to discharge passengers at the floor on which the cafeteria is located and/or at the lower terminal floor.

If there are any passengers in an assigned car at the beginning of an assigned period, the car will answer its registered car call, reverse and by-pass all corridor calls until it arrives at the assigned floor, at which time it is conditioned to receive passengers in the foregoing manner.

If, at the beginning of an assigned period of special service operation, an assigned car is traveling in the down direction below its assigned floor, the car will continue to the lower terminal floor, reverse, and then proceed to its assigned floor. At the conclusion of special service operation, i.e., when the last floor in the predetermined sequence of floors is depopulated, the entire elevator system reverts to normal or off-peak service.

During special service operation, assigned cars continue to return to their assigned floor as long as one of the assigned cars leaves such floor heavily loaded. If no heavily-loaded car leaves the assigned floor within a predetermined time, all assigned cars for that floor preferably are transferred to off-peak operation until cars are assigned to the next succeeding assigned floor.

It will be appreciated that as a result of the special service operation just described, traffic from assigned floors will be appreciably expedited without unduly penalizing traffic at unassigned floors. It should be noted that buildings for which such special service operation is provided generally will have but a single tenant and that, therefore, little or no traffic is to be expected for floors

other than an assigned floor during its associated assigned period.

It is, therefore, an object of the invention to provide an elevator system wherein successive predetermined floors of the structure served by the system are substantially depopulated in accordance with a predetermined sequence.

It is another object of the invention to provide special elevator service for a structure having an elevator system comprising a plurality of elevator cars wherein successive predetermined numbers of cars are assigned to provide service from successive predetermined floors of the structure in only a predetermined direction of travel.

It is a further object of the invention to provide an elevator system as set forth in the preceding object wherein at least one elevator car is conditioned to provide balanced service for all unassigned floors at all times during special service operation.

It is another object of the invention to provide means for starting an assigned elevator car from its assigned floor in the predetermined direction upon the occurrence of a predetermined traffic condition.

It is an additional object of the invention to provide means for starting an assigned elevator car from its assigned floor in the predetermined direction when such car is heavily loaded or at the lapse of a predetermined time, whichever occurs first.

It is also an object of the invention to provide an elevator system as heretofore set forth wherein all assigned cars are transferred to provide balanced service for all floors when no heavily-loaded assigned car leaves the associated assigned floor within a predetermined time.

It is still another object of the invention to provide an elevator system as defined in any of the preceding objects wherein an elevator car assigned to provide special service for a floor is conditioned to ignore all corridor calls for elevator service and all car calls for all floors except those car calls registered for a predetermined floor or for predetermined floors which the elevator car may answer when traveling in the predetermined direction.

Other objects of the invention will be apparent from the following description, taken in conjunction with the accompanying drawings, in which:

FIGURE 1 is a schematic view with circuits shown in straight line form of a portion of an elevator system embodying the invention;

FIGS. 2, 3, 4 and 5 are schematic views with circuits shown in straight line form of further portions of the elevator system illustrated in FIG. 1.

In order to facilitate the orderly presentation of the invention, a number of conventions have been adopted. Although the invention may be incorporated in an elevator system having any desired number of elevator cars serving a structure having any desired number of floors or landings, it will be assumed that the invention is incorporated in an elevator system having four elevator cars serving a structure having six floors or landings. The elevator cars are designated by the reference characters A, B, C and D. Inasmuch as the circuits associated with the four elevator cars are similar, it will suffice to show primarily the circuits associated with the elevator cars A and B. However, certain components associated with the elevator cars C and D also will be referred to.

Because of the similarity of the circuits and components associated with the four elevator cars, components associated with the elevator cars B, C and D will be identified by the same reference characters employed for the components associated with the elevator car A preceded by the appropriate letter B, C or D. For example, the resistors R4, BR4, CR4 and DR4 are associated respectively with the elevator cars A, B, C and D. Consequently the discussion will be directed primarily to the elevator car A and its circuits.

Relays and switches employed for the elevator system may have front or make contacts and back or break contacts. Front or make contacts of a relay are closed when

the relay is energized and picked up. The contacts are open when the relay is deenergized and dropped out. Back or break contacts of a relay are closed when the relay is deenergized and dropped out. The back or break contacts are open when the relay is energized and picked up.

Each set of contacts of a relay or switch is designated by the reference characters employed for the relay or switch followed by a suitable numeral specific to the set of contacts. For example, the reference characters U1 and U3 designate the first and third sets of contacts, respectively, associated with the up switch U of the elevator car A. In the drawings all relays are shown deenergized.

In order further to facilitate the presentation of the invention, certain apparatus specific to the car A and certain apparatus common to all of the elevator cars are set forth as follows:

APPARATUS FOR CAR A

- 20 E—Inductor slowdown relay
- F—Inductor stopping relay
- V—Speed relay
- U—Up switch
- 25 M—Running relay
- D—Down switch
- G—Holding relay
- W—Up preference relay
- X—Down preference relay
- 30 70T—Non-interference relay
- DR—Door relay
- J—Reversing relay
- 1CR through 6CR—Car call registering relays
- T—Car call stopping relay
- 35 50—Car call relay
- 78U—Call-above relay
- S—Floor call stopping relay
- 78—Call relay
- SCCO—No car call relay
- 40 NOX—Assigned floor relay
- SLHT—Dispatching timing relay
- SWR—Auxiliary load relay
- WST—Load relay
- 80N—Dispatching relay
- SLHOB—Car assigning relay

APPARATUS COMMON TO ALL CARS

- 1UR through 5UR—Up floor call registering relays
- 2DR through 6DR—Down floor call registering relays
- SLHD—Special service master relay
- 50 CTX—Transfer relay
- CTA—Timing relay
- 61 and 62—Notching relays
- CLT—Notching timing relay
- NO1 through NO4—Floor selection relays
- 55 CNR—Master car assigning relay
- SWRX—Master load relay

FIGURE 1

FIG. 1 shows the elevator cars A and B and certain control circuits associated therewith. The elevator car A will be assumed to be stopped at the second floor of the structure whereas the elevator car B will be assumed to be stopped at the fifth floor of the structure. With these exceptions, the circuits and mechanisms associated with the two elevator cars are similar and will be understood by the reference to those associated with the elevator car A. Circuits for the elevator car A are shown in the left-hand column of FIG. 1, while circuits for the car B are illustrated in the right-hand column thereof.

The elevator car A is connected by a rope or cable 10 to a counterweight 11. The rope 10 passes over a sheave 12, which is secured to a shaft 13 for rotation therewith. The shaft 13 is rotated by a motor 14 which may be of any conventional type. For present purposes

it will be assumed that the motor 14 is a direct current motor having its armature 14A secured to the shaft 13 and having a field winding 14F which is permanently connected across two direct current buses L1 and L2 which supply direct current energy for the control circuits.

The elevator car A has therein a plurality of normally-open car-call push-buttons 1c through 6c (FIG. 2) which are actuated for the purpose of registering calls respectively for the first through sixth floors as desired by passengers entering the elevator car.

To permit registration of calls for service by prospective passengers located at the various floors served by the elevator cars, push-button stations are located at such floors. Such a station is shown in FIG. 1 for the third floor. It includes a normally-open up floor call push-button 3U which is pressed by a prospective passenger desiring elevator service in the up direction. A similar push-button is located at each floor from which service in the up direction may be desired. The station also includes a normally-open push-button 3D which is pressed by a prospective passenger desiring elevator service in the down direction. A similar push-button is located at each floor from which elevator service in the down direction may be desired. The numeral of the reference characters (as 3D or 3U) indicates the floor at which the push-button is located.

The elevator car A also has mounted thereon an inductor slowdown relay E and an inductor stopping relay F which may be of conventional construction. The slowdown relay E has two sets of break contacts E1 and E2 associated therewith. The relay has a normally incomplete magnetic circuit, and initial energization of the winding of the relay alone does not initially open the associated contacts. However, if the slowdown relay E reaches an inductor plate UEP located in the hoistway of the elevator car while the winding of the relay is energized, the contacts E1 open. The inductor relay may be of the type which when it opens its contacts maintains the contacts open until the relay winding is de-energized even though the relay passes beyond the inductor plate. In FIG. 1 the inductor plate UEP is assumed to be mounted in the hoistway to be reached by the slowdown relay E as the elevator car A nears the third floor. If the elevator car A, during up travel thereof, is to stop at the third floor, the winding of the relay E is energized, and, when the relay reaches the inductor plate UEP for the third floor, the contacts E1 open to initiate a slow-down operation for the elevator car. It will be understood that a similar inductor plate similarly is associated with each of the floors at which the elevator car A may stop during up travel thereof.

During down travel of the elevator car A, the inductor relay E cooperates with down inductor plates DEP to initiate a slow-down of the elevator car as it approaches a floor at which the elevator car is intended to stop. For example, if the elevator car is to stop during down travel at the third floor, the winding of the inductor relay E is energized as the elevator car nears the third floor. When the inductor relay reaches the down inductor plate DEP for the third floor, the contacts E2 open to initiate a slow-down operation of the elevator car. It will be understood that a similar inductor plate DEP is provided for each of the floors at which the elevator car A is to stop during down travel thereof.

The stopping relay F similarly cooperates with inductor plates UFP and DEP for the purpose of bringing the elevator car to a stop as it reaches a floor at which it is to stop. Thus, if the elevator car A during up travel is to stop at the third floor, the winding of the stopping relay F is energized and as the inductor stopping relay F reaches the stopping inductor plate UFP for the third floor, the contacts F1 open. These contacts in opening result in stopping of the elevator car at the third floor. A similar inductor plate is provided for each of the floors

at which the elevator car A is to stop during up travel thereof.

If the elevator car A is to stop at the third floor during down travel thereof, the winding of the stopping relay 5 is energized, and, as the relay reaches the inductor plate DFP for the third floor, the contacts F2 open to produce a stopping operation of the elevator car at the third floor. It will be understood that a similar inductor plate is provided for each of the floors at which the elevator car A 10 is to stop during down travel thereof.

Because of the large number of control circuits required, it is conventional practice to provide each elevator car with a floor selector 16. This selector includes a plurality of rows of contact segments mounted on an insulating panel 16A. Only two rows of contact segments a1 through a5 and d1 through d5 are illustrated in FIG. 1. The contact segments are successively engaged during travel of the elevator car respectively by brushes aa and dd for the purpose of controlling the energization of certain circuits. For example, if the elevator car A during down travel is to stop at the third floor in response to a car call, the brush aa engages the contact a3 shortly before the elevator car A reaches the third floor, to initiate a stopping operation thereof.

25 The brushes aa and dd are mounted on a brush carriage 16C, which is mounted for movement in accordance with movement of the elevator car, but at a greatly reduced rate. In the embodiment of FIG. 1, it is assumed that the carriage 16C has threaded engagement with a screw 30 16S, which is coupled to the shaft 13 through suitable gearing for rotation in accordance with of the elevator car A. Consequently, as the elevator car A moves, the brushes mounted on the carriage 16C permit the energization of appropriate circuits at various points of travel of the elevator car.

35 Although the driving motor 14 may be energized in various ways, it will be assumed that the control of this motor is of the type commonly referred to as a variable voltage control. In such a control, a direct current generator 17 has its armature 17A connected in a loop with the armature 14A of the motor. A series field winding 17S for the generator also may be included in this loop. The generator has a main field winding 17F, which is connected for energization from the buses L1 and L2 40 through a reversing switch. This reversing switch includes contacts U2 and U3 of an up switch. When these contacts are closed, the field winding is energized with proper polarity for up travel of the elevator car. On the other hand, when contacts D2 and D3 of a down switch are 45 closed, the field winding is energized with proper polarity for down travel of the elevator car. The energization of the field winding is completed through a resistor R1 for slow-speed operation of the elevator car or through make contacts V1 of a speed relay for full-speed operation of 50 the elevator car.

55 The elevator car A is provided with a conventional spring-applied electromagnetically-released brake. This brake includes a brake drum 18D which is secured to the shaft 13 for rotation therewith. A brake shoe 18C normally is biased against the brake drum by means of a spring (not shown). The brake is released upon energization of a brake coil 18B, which cooperates with a magnetic armature 18A secured to the shoe 18C. The coil 18B is connected to the buses L1 and L2 for energization either through make contacts U1 or through make contacts D1 of the up switch U or the down switch D, respectively.

70 The speed relay V is connected for energization from the buses L1 and L2 through either of two paths. One of these paths includes make contacts U4 of the up switch a limit switch 19 and the break contacts E1 of the slowdown relay. The limit switch 19 is cam-operated normally-closed switch which is opened as the elevator car nears its upper limit of travel.

The remaining path of energization comprises the make contacts D4 of the down switch, a limit switch 20 and the break contact E2 of the slowdown relay. The limit switch 20 may be cam-operated. It is normally closed and is opened as the elevator car A nears its lower limit of travel.

As long as the elevator car A is running, the running relay M is energized. This relay can be energized only as long as the make contacts DR1 of a door relay DR are closed. The contacts are closed only as long as all of the hoistway doors and car doors for the car A are closed. Such safety provisions are well known in the art.

The running relay M initially can be energized only if the break contacts 70T1 are closed to indicate that a predetermined minimum time has elapsed since the last stop of the elevator car A to permit discharge or entry of passengers and if the make contacts 80N1 of the dispatching relay 80N are closed.

Assuming that the foregoing contacts associated with the running relay M are closed, the relay may be energized initially through either of two paths. One of these paths is as follows:

L1, 80N1, 70T1, W1, F1, 21, U, M, DR1, L2

Since the up switch U is energized through this path, it follows that the elevator car will be conditioned for up travel. The limit switch 21 is a normally-closed mechanically-operated switch which is opened as the elevator car A nears its upper limit of travel. When energized, the up switch U closes its make contacts U5 to establish a holding circuit around the contacts 80N1, 70T1, and W1.

The second path for initially energizing the running relay M may be traced as follows:

L1, 80N1, 70T1, X1, F2, 22, D, M, DR1, L2

Since the down switch D now is energized, it follows that the elevator car A is conditioned for down travel. The limit switch 22 is a mechanically-operated normally-closed switch which is opened as the elevator car A nears its lower limit of travel. When it picks up, the down switch D closes its make contacts D5 to establish a holding circuit around the contacts 80N1, 70T1 and X1.

If the elevator car A is to be operated by a car attendant, the contacts 80N1 and 70T1 may be replaced by a manually-operated switch which is closed by the car attendant when the car is to be moved from a floor at which it is stopped. However, in a preferred embodiment of the invention, the automatically-operated contacts 80N1 and 70T1 are employed.

The inductor slowdown relay E, the inductor stopping relay F and a holding relay G are energized in parallel from the buses L1 and L2 through the make contacts M1 of the running relay M. To complete an energizing circuit for these relays E, F and G, one of the following conditions must be present: first, the make contacts T1 are closed to indicate that a car call is registered for a floor which the elevator car A is approaching. Second, the make contacts S1 are closed to indicate that the elevator car A is conditioned to stop at a floor in answer to a registered floor call for such floor.

When the holding relay G is energized, it closes its make contacts G1 to establish with the make contacts M1 a holding circuit for the inductor relays E and F.

The door relay DR is connected across the buses L1 and L2 through door safety interlock contacts respectively operated by each door associated with the elevator car A. If any of the doors is open, the contacts associated therewith also are open to prevent energization of the door relay DR.

The direction of travel of the elevator car A is determined initially by an up preference relay W and a down preference relay X. For the up preference relay W to be energized, the break contacts D6 must be closed (i.e. the down switch D is energized) and the break contacts X2 must be closed (i.e. the down preference

relay X is deenergized). The limit switch 23 also must be closed. This switch is normally closed and is opened as the elevator car A reaches its upper limit of travel, in this case the sixth floor.

Energization of the up preference relay W also requires closure of at least one of two sets of contacts. These include the break contacts J1, which are closed when the elevator car A is not conditioned to reverse at the nearest floor in its direction of travel. Make contacts M2 are closed as long as the elevator car A is running.

The down preference relay X is energized if the break contacts U6 are closed (i.e. the up switch U is deenergized), the break contacts W2 are closed (i.e. the up preference relay is deenergized) and the limit switch 24 is closed. This limit switch is normally closed and is opened as the elevator car A reaches the lower terminal floor.

As long as the elevator car A is running, the make contacts M3 are closed to energize the non-interference relay 70T. When the elevator car A stops, the contacts M3 open to deenergize the relay. However, the relay 70T has a substantial delay in dropout. This delay may be provided in any suitable manner, as by connecting a resistor R2 across the relay coil. The time delay in dropout is selected to be sufficient to permit discharge of passengers from the elevator car A or entry of passengers into the elevator car A after each stop.

Energization of the high call reversal relay J prepares the elevator car A to reverse during up travel at the nearest floor. The relay J may be energized if the elevator car A is conditioned for up travel (break contacts X3 are closed) or if the break contacts M4 are closed to indicate that the elevator car A is not running, if the make contacts SLHOB1 are closed to indicate that the car A is conditioned for special service operation and if the make contacts 78U1 are closed to indicate that no higher calls remain to be answered (in some cases no higher car calls).

When the reversing relay J is energized, its make contacts J2 close to establish a holding circuit therefor through the break contacts X3 or M4.

FIGURE 2

FIG. 2 shows the car call registration circuits for the elevator cars A and B and the circuits for energization of their respective car call relays 50 and B50.

It will be recalled that the elevator car A is provided with a plurality of push-buttons 1c through 6c for the purpose of registering car calls. Each of these push-buttons has associated therewith a car call registering relay 1CR through 6CR, respectively. The push-buttons and call registering relays cooperate with four rows of contact segments located on the floor selector for the elevator car A. The contact segments a1 through a5 cooperate with the brush aa for the purpose of initiating a stopping operation of the elevator car during down travel of the elevator car respectively at the first through fifth floors. The contact segments b2 through b6 cooperate with a brush bb for the purpose of initiating a stopping operation of the elevator car during up travel of the elevator car respectively at the second through sixth floors. A brush cc cooperates with a row of contact segments c2 through c6 and a brush dd cooperates with a row of contact segments d1 through d5 for the purpose of cancelling registered car calls as they are answered respectively during down travel and up travel of the elevator car. It will be understood that for each contact segment the numeral of the reference character designates the floor with which the contact segment is associated. Thus, the reference character a1 designates the contact segment for the first floor in the a row.

Assuming that the elevator car A is not conditioned to provide special service and that the no car call relay SCPO, therefore, is deenergized, by reference to FIG. 2 it will be observed that when the car call push-button

5c is pressed the car call registering relay 5CR is connected therethrough and through break contacts SCCO3 across the buses L1 and L2. This relay closes its make contacts 5CR1 to establish a holding circuit around the push-button and the contacts SCCO3. The contact segments a5 and b5 then are connected through the contacts 5CR1 to the bus L1.

If the elevator car A is set for down travel, the make contacts X4 are closed; and if the elevator car is approaching the fifth floor, the make contacts M5 of the running relay also are closed. Consequently, as the elevator car nears the fifth floor the brush aa engages the contact segment a5 to complete the following energizing circuit for the car call stopping relay T:

L1, 5CR1, a5, aa, X4, T, M5, L2

The energization of the relay T initiates a stopping operation of the elevator car A at the fifth floor.

As the elevator car A continues its approach toward the fifth floor, the contact segment c5 is engaged by the brush cc. As the elevator car comes to a stop, the break contacts M6 of the running relay close to complete the following cancelling circuit:

L1, 5CR1, 5CRN, c5, cc, X5, M6, L2

The operating coil of the registering relay 5CR and the cancelling coil 5CRN are wound in opposition on a common core. Consequently, energization of the cancelling coil 5CRN cancels the effect of the operating coil and resets the registering relay 5CR. Preferably, as the elevator car stops at the fifth floor, the brush aa passes slightly below the associated contact segment a5; however, the brush cc remains in engagement with the associated contact segment c5 as long as the elevator car A remains at the floor.

Next it will be assumed that the same call is registered for the fifth floor as the elevator car A travels up toward the fifth floor. Under these circumstances, the make contacts W4 and W5 of the up preference relay are closed. As the elevator car A nears the fifth floor, the brush bb engages the contact segment b5 to complete the following circuit:

L1, 5CR1, b5, bb, W4, T, M5, L2

The energization of the car call stopping relay T results in the initiation of a stopping operation for the fifth floor.

As the elevator car A continues to approach the fifth floor, the brush dd engages the contact segment d5. As the elevator car comes to a stop, the break contacts M6 of the running relay close to complete the following circuit:

L1, 5CR1, 5CRN, d5, dd, W5, M6, L2

The energization of the cancelling coil 5CRN resets the car call registering relay 5CR. During the stopping operation, the brush bb preferably passes slightly above the associated contact segment b5, whereas the brush dd remains in engagement with the associated contact segment d5 as long as the elevator car A is at the fifth floor.

The car call registering circuits for all of the intermediate floors are similar to those described for the fifth floor. It will be noted, however, that break contacts W3 of the up preference relay W parallel break contacts SCCO8 in the circuit of the second floor car call registering relay 2CR. The effect of these contacts on operation of the car A will be discussed hereinafter in the section entitled, Special Service Operation.

The car call registering circuits for the upper terminal (sixth floor) may be similar to those employed for the intermediate floors. However, since the elevator car A tops at the sixth floor only during up travel, contact segments for the sixth floor need not be provided in the a and d rows. By reference to FIG. 2, it will be noted that

only contact segments b6 and c6 are provided for the sixth floor.

The car call registering circuits for the lower terminal or first floor may be similar to those provided for the intermediate floors. Since the elevator car stops at the first floor only during down travel, contact segments for the first floor need not be provided in the b and c rows. For this reason, in the car call registering circuits only contact segments a1 and d1 are illustrated for the first floor. Since the car A always must stop at the first floor during down travel thereof, the contact segment a1 is connected permanently to the bus L1 to insure energization of the relay T and a resulting stopping operation of the car during such travel.

15 It will be observed in FIG. 2 that contacts of the no car call relay SCCO and of the floor selection relays NO1 through NO4 are associated with some of the car call registering circuits for the elevator cars A and B but not with other car call registering circuits thereof. The 20 operation of these contacts will be discussed hereinafter in the section entitled, Special Service Operation.

The lower part of FIG. 2 illustrates circuits associated with the car call relays 50 and B50. In order for these relays to be energized, make contacts SLHO1 and 25 SLHO2, respectively, must be closed to indicate that the special service master relay SLHO is energized and picked up. In series with the relay 50 for the car A are parallel make contacts 1CR2 through 6CR2 of the car call registering relays 1CR through 6CR, respectively. 30 Thus, if a car call is registered for the car A, closure of the corresponding set of make contacts 1CR2 through 6CR2 results in energization of the car call relay 50, provided the contacts SLHO1 also are closed. The closure of additional contacts upon the registration of 35 additional car calls for the car A merely provides additional paths for energization of the relay 50. It will be apparent that the relay 50, once energized, cannot drop out until all of the car calls registered for the elevator car A are answered by the car A. The car call relay B50 operates similarly in response to the registration of car calls for the car B.

FIGURE 3

The upper part of FIG. 3 illustrates up floor call 45 registering circuits for the elevator cars. These circuits are operated by means of normally-open push-buttons 1U through 5U common to all of the elevator cars and located respectively at the first through fifth floors. The push-buttons have associated therewith up floor call registering relays 1UR through 5UR and cancelling coils 1URN through 5URN in a manner which will be clear from the discussion of the call registering relays and cancelling coils associated with the car call push-buttons of FIG. 2.

55 The up floor call registering relays 1UR through 5UR and their cancelling coils are associated with contact segments for each of the elevator cars in the bank. For example, a row of contact segments e2 through e6, respectively for the second through sixth floors, is provided for the elevator car A and cooperates with a brush ee. A brush ff cooperates with a row of contact segments f1 through f5, respectively for the first to fifth floors for the elevator car A.

60 Let it be assumed that while the elevator car A is traveling up a prospective passenger waiting at the fifth floor presses the up floor call push button 5U to energize the up floor call registering relay 5UR. This relay closes its make contact SUR1 to establish a holding circuit around the push button.

65 Since the elevator car is assumed to be traveling up, the make contacts W6 and W7 of the up preference relay W are closed. It will be assumed further that the break contacts SLHOB2 and SLHOB3 of the car assigning relay SLHOB are closed to indicate that the car A is not assigned to provide special service. As the elevator car

11

A nears the fifth floor, the brush *ee* engages the contact segment *e5* to complete the following circuit:

L1, 5UR1, *e5*, *ee*, W6, S, SLHOB2, L2

The energization of the floor call stopping relay S initiates the stop at the fifth floor. In response to movement of the car toward the fifth floor, the brush *ff* engages its contact segment *f5*. As slowdown of the elevator car is initiated, the break contacts V2 close to complete the following cancelling circuit:

L1, 5UR1, 5URN, *f5*, *ff*, W7, SLHOB 3, V2, L2

This resets the up floor car registering relay 5UR. As the elevator car A comes to a stop, the brush *ee* preferably passes slightly above the contact segment *e5*. However, the brush *ff* remains in engagement with the contact segment *f5* as long as the elevator car A remains at the fifth floor.

By inspection of FIG. 3, it will be observed that the contact segment *e5* is connected to corresponding contact segments for the other elevator cars in the bank (such as contact segment *Be5* for the elevator car B). Similarly, the contact segment *f5* is connected to corresponding contact segments (such as the contact segment *Bf5*) for the remaining cars of the bank. Consequently, operation of the push button 5U is effective to stop the first up-traveling elevator car which reaches the fifth floor and which is conditioned to accept the call at the fifth floor.

As will be observed in FIG. 3, the up floor call registering circuits for all of the intermediate floors are similar. During up travel, the elevator cars always must stop at the sixth floor if they reach such floor. For this reason, a single contact segment *e6* for the car A suffices for the sixth floor and is connected permanently to the bus L1. Since the elevator car A does not stop during up travel at the lower terminal or first floor a contact segment in the *e* row is not required for the first floor. With these exceptions, the call registering circuits for the first and sixth floors are similar to those described for the fifth floor.

The lower part of FIG. 3 illustrates the down floor call registering circuit for the elevator cars. Down floor calls are registered by operation of normally-open push buttons 2D through 6D for the second through sixth floors, respectively, and have associated therewith down floor call registering relays 2DR through 6DR and cancelling coils 2DRN through 6DRN. Each push button cooperates with its call registering relay and its cancelling coil in the manner discussed with reference to the up floor call push buttons. For the elevator car A, a row of contact segments *g1* through *g5* cooperates with a brush *gg*, a row of contact segments *h3* through *h6* cooperates with a brush *hh*, and a row of contact segments *j2* through *j6* cooperates with a brush *jj*.

Let it be assumed that the elevator car A while traveling down is approaching the fourth floor, at which a down floor call has been registered by operation of the push button 4D. Such operation results in energization of the down floor call registering relay 4DR to close the make contacts 4DR1. Since the elevator car is traveling down, the make contacts X6, X7 and 70T2 are closed. It will be assumed that the break contacts SLHOB2 and SLHOB3 are closed.

As the elevator car A nears the fourth floor, the brush *gg* engages the contact segment *g4* to complete the following circuit:

L1, 4DR1, *g4*, *gg*, X6, S, SLHOB2, L2

The energization of the floor call stopping relay S initiates a stopping operation of the elevator car A at the fourth floor.

As the elevator car continues its approach the brush *hh* engages the contact segment *h4* and the brush *jj* engages the contact segment *j4*. The initiation of slow-

12

down of the elevator car A results in closure of the break contacts V2 to complete the following cancelling circuits:

L1, 4DR1, 4DRN, *h4*, *hh*, 70T2, SLHOB3, V2, L2.
L1, 4DR1, 4DRN, NO2-3 and CTX3 in parallel *j4*,
jj, X7, SLHOB3, V2, L2

The energization of the cancelling coil resets the call registering relay 4DR. Preferably, as the elevator car A comes to a stop, the brush *gg* passes slightly below the associated contact segment *g4*, but the brushes *hh* and *jj* remain in engagement with their respective associated contact segments *h4* and *j4*.

The contact segment *g4* is connected to corresponding contact segments (such as the contact segments *Bg4*) of the remaining cars, and the contact segment *h4* is connected to corresponding contact segments (such as the contact segment *Bh4*) of the remaining cars. Similarly, the contact segment *j4* is connected to corresponding contact segments (such as the contact segment *Bj4*) for the remaining cars. Consequently, the first elevator car to approach the fourth floor while traveling down will answer a call registered by the call registering relay 4DR.

The down floor call registering circuits for all of the intermediate floors are similar and may be traced readily in FIG. 3. (It will be observed that the down floor call registering circuit for the second floor has no contact segment in the *h* row and that the contact segments *j2* and *Bj2* are connected directly to the cancelling coil 2DRN. For purposes of the present discussion, these differences are immaterial and the reasons therefor will be readily understood from the description of special service operation hereinafter.) The down floor call registering relay circuit for the upper terminal or sixth floor also may be similar. However, since the elevator car A does not stop at the sixth floor during down travel, the contact segment in the *g* row may be omitted for the sixth floor. Since the elevator car A always must stop at the lower terminal floor, a single first floor contact segment *g1* may be provided for the elevator car A for the first floor, and this contact segment may be connected permanently to the bus L1.

FIGURE 4

In FIG. 4 a call circuit 30 for car A is provided which has two functions. This circuit energizes a call relay 78 when no call is registered by operation of the car call push buttons for the elevator car A and by any floor call push button. In addition, the call circuit 30 energizes the call-above relay 78U as the elevator car during up travel thereof nears the highest floor for which a down floor call or a car call is registered provided no up floor call is registered for such floor or for a higher floor.

The call circuit 30 includes break contacts for all of the floor call registering relays and for all of the elevator car A car call registering relays arranged in the order of the floors. This circuit may be traced as follows:

L1, 6CR3, 6DR2, 5UR2, 5CR3, 5DR2, 4UR2, 4CR3, 4DR2, 3UR2, 3CR3, 3DR2, 2UR2, 2DR2, 2CR3, 1CR3, 1UR2, 78, L2

60 By inspection of this circuit, it will be observed that as long as a call is registered by operation of the car call push buttons the relay 78 is deenergized.

The call circuit 30 has associated therewith a row of contact segments *k2* through *k6* which are engaged successively by the brush *kk* as the elevator car A moves. The contact segments *k2* through *k5* for the second through fifth floors, respectively, are so located relative to the call circuit 30 that each contact segment is placed below all break contacts of the call circuit which require travel of the elevator car A above such contact segment. Thus, the contact segment *k5* is connected to the call circuit between the contacts 5UR2 and 5CR3. The contact segment *k4* is connected between the contacts 4UR2 and 4CR3. The location of the remaining intermediate floor

contact segments similarly may be ascertained by reference to FIG. 4. It will be noted that the contact segment *k6* is connected directly to the bus *L2* and that the relay *78U* is connected between the brush *kk* and the bus *L2* through make contacts *W8* of the up preference relay *W*.

In certain cases, it is desirable to prevent registered calls from affecting the call circuit 30. For example, it may be desirable under some conditions to prevent registered floor calls from affecting the operation of the relays *78U* and *78*. To this end, make contacts of the car assigning relay *SLHOB* are provided for the purpose of shunting the break contacts of the floor call relays for floors above the first floor. When the relay *SLHOB* is energized, the contacts *SLHOB4* through *SLHOB7* close to shunt the break contacts *5UR2* through *2UR2* and *6DR2* through *2DR2*.

FIG. 4 also illustrates circuits associated with special service operation of the elevator cars A and B. If the elevator car A is assigned to special service operation, the make contacts *SLHOB8* are closed. In order for the no car call relay *SCCO* to be energized, the break contacts *70T3* must be closed to indicate that the non-interference relay *70T* has dropped out, and the break contacts *50-1* must be closed to indicate that no car call remains to be answered by the elevator car A. Pickup of the relay *SCCO* is accompanied by closure of its make contacts *SCCO9* to establish a holding circuit for the relay. Thus, once the relay *SCCO* is energized, it remains picked up through its holding contacts *SCCO9* and through the make contacts *SLHOB8* as long as the elevator car A is assigned to special service operation.

The assigned floor relay *NOX* for the elevator car A is associated with a row of contact segments *m3*, *m4* and *m6*, which are engaged successively by a brush *mm* as the elevator car A moves. The contact segments *m3*, *m4* and *m6* are associated, respectively, with the third, fourth and sixth floors, the contact segments being connected to the bus *L1* through respective make contacts *NO3-3*, *NO2-4* and *NO1-4*. If the elevator car A is assigned to provide special service, one of the latter sets of contacts will be closed. Assume, for example, that the car A is assigned to provide special service for the sixth floor. As the car A arrives at the sixth floor, the brush *mm* engages the contact segment *m6* to establish the following circuit:

L1, NO1-4, *m6*, *mm*, *NOX*, *SLHOB8*, *L2*

Energization of the relay *NOX* is accompanied by closure of its make contacts *NOX1*. If the non-interference relay *70T* has dropped out to close its break contacts *70T4*, a holding circuit through the contacts *70T4* and *NOX1* is established for the relay *NOX*.

It will be observed that the assigned floor relay *BNOX* for the elevator car B also has a brush and a row of contact segments associated therewith. In the case of the elevator car B, however, the contact segments *Bm4*, *Bm5* and *Bm6* are provided for the fourth, fifth and sixth floors, respectively. The reasons for the differences in the contact segments in the *m* rows for the cars A and B will be apparent from the description of operation hereinafter.

As long as the make contacts *SLHOB8* are closed and non-interference relay *70T* for the elevator car A remains picked up to maintain its make contacts *70T5* in closed condition, the dispatching timing relay *SLHT* is energized. When the non-interference relay times out, the contacts *70T5* open to deenergize the relay *SLHT*. However, the relay *SLHT* has a substantial delay in dropout. This delay may be provided in any suitable manner, as by connecting a resistor *R3* across the relay coil. The time delay in dropout is selected to be sufficient to permit the entry of a relatively large number of passengers into the elevator car A at an assigned floor. In a preferred embodiment of the invention, the time delay may be of the order of 15 seconds.

Energization of the auxiliary load relay *SWR* indicates

that the elevator car A is at its assigned floor (make contacts *NOX2* are closed), that the elevator car A is loaded (break contacts *W5T1* are closed) and that all of the doors associated with the elevator car A are closed (make contacts *DR2* are closed). Thus, pickup of the relay *SWR* signifies that the car A is loaded and is about to leave its assigned floor.

Energization of the load relay *W5T* is controlled by a load weighing switch *WH*. When sufficient load has entered the elevator car, the switch *WH* opens to drop out the relay *W5T*. Such switches are well known in the art. The switch *WH* may be adjusted to open when the elevator car A is approximately 80% fully loaded. Desirably, the relay *W5T* is provided with a short time delay in dropout such as one second. This delay may be provided in any suitable manner as by connecting a resistor *R4* across the relay coil.

The dispatching relay *80N* may be energized if one of the following conditions is present: First, the break contacts *78-1* are closed to indicate that a call for service which may be answered by the car A has been registered, and the break contacts *SCCO10* are closed to indicate that the elevator car A is not conditioned for special service operation. Second, the break contacts *J3* are closed to indicate the elevator car A is not conditioned to reverse at the next floor reached by the elevator car or at the floor at which it is stopped (with the exception of the lower terminal floor) and the make contacts *SCCO11* are closed to indicate that the car A is conditioned for special service operation. Third, the make contacts *J4* are closed to indicate that the elevator car A is conditioned to reverse at the next floor reached by the elevator car during up travel thereof or at the floor at which it is stopped (with the exception of the lower terminal floor).

Additionally, in order for the relay *80N* to be energized, one of the following conditions must be satisfied: If the car A is located at an assigned floor during special service operation and if the dispatching time for the car has expired, the break contacts *SLHT1* are closed. If the car A is loaded during special service operation the break contacts *W5T2* are closed. If the car A is not located at an assigned floor during special service operation, the break contacts *NOX3* are closed. Finally, if the no car call relay *SCCO* for the car A is dropped out, its break contacts *SCCO12* are closed. Pickup of the relay *80N* results in the starting of the elevator car A from a floor at which it has stopped both during off-peak operation and during special service operation.

When the elevator system is conditioned to provide special service operation, it may be desirable to provide suitable information for system passengers. For example, during such operation an assigned elevator car does not provide up service. A sign may be operated at each floor to present such information to system passengers. In FIG. 4 such signs *101* are connected between the buses *L1* and *L2* through make contacts *SLHOB9* of the car assigning relay *SLHOB*. The signs *101* conveniently may be located adjacent the elevator car A at the various floors of the building.

FIGURE 5

FIG. 5 illustrates apparatus common to the elevator cars A, B and C for special service operation.

A master clock *1BM* and a one-half hour clock *1BH* are connected directly across the buses *L1* and *L2*. The master clock *1BM* is a twenty-four hour clock which has a set of contacts that close to initiate special service operation and that open shortly thereafter. The one-half hour clock has make contacts which close and break contacts which open for a period of approximately two minutes at the start of each of a plurality of special service assignment periods. Since the special service operation described herein is particularly suitable for lunch hour periods, it will be assumed that the master clock *1BM* has make contacts which close at 11:14 a.m. and

that the one-half hour clock has make contacts which close and break contacts which open for approximately two minutes at each of the following times: 11:15 a.m.; 11:25 a.m.; 11:31 a.m.; 11:35 a.m.; and 11:42 a.m. Such clocks are well known in the art, and it appears unnecessary to describe them further.

Assuming that a manually-operable switch 103 is in closed condition, the special service master relay SLHO initially is energized through closure of the make contacts 1BM1 of the master clock 1BM in series with parallel break contacts NO4-4 and 61-1. Pickup of the relay SLHO is accompanied by closure of its make contacts SLHO3 to establish a holding circuit for the relay through the aforementioned parallel contacts. At the termination of special service operation, the contacts NO4-4 and 61-1 simultaneously open to drop out the special service master relay SLHO. The switch 103 is provided in the event that it is desired to prevent the elevator system from providing special service operation. On weekends, for example, when the building is lightly populated, the switch 103 may be placed in open condition. It will be assumed for purposes of the present discussion, however, that the switch 103 is in closed condition.

Energization of the relay SLHO also is accompanied by closure of its make contacts SLHO4 to provide direct current energization for the bus L2A and thus for the circuits of FIG. 5 below these contacts. For the remainder of the discussion of FIG. 5, it will be assumed that the relay SLHO is energized and, therefore, that its make contacts SLHO4 are closed.

Energization of the transfer relay CTX signifies that heavy demand for down service from an assigned floor has terminated before the end of the associated assigned period of special service operation. Pickup of the relay CTX initially is effected through series make contacts CTA1 and SWRX1. When the relay CTX picks up, a holding circuit is established therefor through its make contacts CTX5 and through a plurality of break contacts of the floor selection relays NO1 through NO4, as will be apparent from inspection of FIG. 5. Subsequent dropout of the relay CTX may occur under any one of the following conditions: the parallel break contacts NO1-6 and NO2-6 open simultaneously at the termination of the first assigned period of special service operation; the parallel break contacts NO2-7 and NO3-4 open simultaneously at the termination of the second assigned period of special service operation; the parallel break contacts NO3-5 and NO4-5 open simultaneously at the end of the third assigned period of special service operation or the make contacts SLHO4 open at the end of the fourth assigned period of special service operation.

Energization of the individual car assigning relays SLHOB, BSLHOB and CSLHOB initially is controlled by make contacts CNR1 of the master car assigning relay CNR. If the contacts CNR1 are closed, energization of the individual car assigning relays is further controlled by contacts of the floor selection relays NO2 through NO4. Thus, if the contacts CNR1 are in closed condition, the car assigning relay SLHOB for the elevator car A may be energized for all assigned periods of special service operation except the fourth period, when the break contacts NO4-6 are open; the car assigning relay BSLHOB for the elevator car B may be energized for all assigned periods of special service operation except the third period, when the break contacts NO3-6 are open; and the car assigning relay CSLHOB for the elevator car C may be energized for all assigned periods of special service operation except the second and third periods, when the break contacts NO2-8 and NO3-7, respectively, are open.

The timing relay CTA may be of any suitable construction capable of providing the desired timing operation. In the embodiment illustrated in FIG. 5, the relay is controlled electronically by circuits including an electronic device such as a tube TU1. This tube may be of

any suitable type and may be either of the high-vacuum or gaseous-discharge type. In a preferred embodiment of the invention, the tube TU1 is a gaseous-discharge tube of the type known as thyratron. This thyratron may be

5 either of the cold cathode or of the hot cathode type.

The tube TU1 has a plate electrode 310, a cathode electrode 311, and a control or grid electrode 312. The voltage between the grid and cathode electrodes is determined by a capacitor CA1. The capacitor is dis-
10 charged through a path which includes a resistor R5 and either make contacts SWR2, BSWR2 or CSWR2 of the respective auxiliary load relays of the elevator cars A, B and C or break contacts CNR3 of the master car assigning relay CNR.

15 When the capacitor CA1 is to be charged, it is connected across the buses L1 and L2 through a circuit which includes a resistor R6, break contacts CSWR1, BSWR1 and SWR1 and make contacts CNR2. The bus L1 may represent the positive terminal of the direct
20 current source of electrical energy.

When the tube TU1 fires or has a discharge initiated between the plate and cathode electrodes, the timing relay CTA picks up and closes its make contacts CTA2 to establish a holding circuit around the tube TU1 through
25 a resistor R7. Closure of the contacts CTA2 also results in the shunting of the plate and cathode electrodes of the tube by the resistor R7 to terminate the discharge in the tube.

The operation of the timing relay CTA now will be
30 considered in detail. It will be assumed initially that the master car assigning relay CNR has picked up to close its make contacts CNR2 and to open its break contacts CNR3. Immediately prior to such operation, the timing relay CTA was deenergized. Opening of the contacts
35 CNR3 interrupts the discharge circuit for the capacitor CA1, since under the assumed conditions the parallel make contacts SWR2, BSWR2 and CSWR2 also are open.

Closure of the make contacts CNR2 results in completion of the following charging circuit for the capacitor
40 CA1:

L1, CNR2, SWR1, BSWR1, CSWR1, R6, CA1, L2

The capacitor CA1 now starts to charge at a rate determined by the resistance and the capacitance of the charging circuit.

45 Upon expiration of the time required for the voltage across the capacitor CA1 to build up to a suitable value, the tube TU1 fires to establish the following energizing circuit for the timing relay CTA:

50 L1, CNR2, SWR1, BSWR1, CSWR1, CTA, 310, 311, L2
If desired, the resistor R6 may have an adjustable resistance or the capacitor CA1 may have an adjustable capacitance, or both may be adjustable for the purpose of adjusting the time delay in pickup of the relay CTA.

55 In picking up the relay CTA closes its make contacts CTA2 to establish a holding circuit around the tube TU1 through the resistor R7. Inasmuch as the contacts CTA2 and the resistor R7 shunt the plate and cathode electrodes of the tube TU1, the discharge between such
60 electrodes is terminated.

Although the specific time delay in pickup of the relay CTA will depend upon the requirements of each specific elevator installation, it will be assumed in the present system that the relay CTA is designed to pick up with a time delay of the order of 90 seconds.

Let it be assumed in the preceding example that after the relay CNR picks up to close its make contacts CNR2 to initiate the charging of the capacitor CA1, the relay SWR picks up to open its break contacts SWR1 and to
70 close its make contacts SWR2 before the capacitor CA1 charges sufficiently to initiate a firing of the tube TU1, i.e., before the expiration of 90 seconds after the closure of the make contacts CNR2. Opening of the contacts SWR1 interrupts the charging circuit of the capacitor CA1, while closure of the make contacts SWR2 estab-

75

lishes a discharge path for the capacitor CA1 through the resistor R5. Thus, as long as at least one of the auxiliary load relays SWR, BSWR or CSWR picks up before the expiration of the 90 second period, the timing relay CTA is prevented from picking up. Subsequent dropout of the auxiliary load relay results in the initiation of a timing operation of the timing relay CTA.

Operation of the notching relays 61 and 62, the notching timing relay CLT, the floor selection relays NO1 through NO4 and the master car assigning relay CNR now will be described.

Assuming that the manually operated switch 103 is in closed condition, at 11:14 a.m., as heretofore noted, the special service master relay SLHO will pick up through the make contacts 1BM1 of the master clock 1BM to close the make contacts SLHO4 to provide direct current energization for the circuits of FIG. 5 connected to the bus L2A below these contacts. Closure of the make contacts SLHO3 results in the establishment of a holding circuit for the special service master relay SLHO. (It will be recalled that the make contacts 1BM1 reopen after the expiration of a relatively short time interval.)

When the make contacts SLHO4 close, the notching timing relay CLT is energized through the closed break contacts 1BH2 on the one-half hour clock 1BH. Closure of the make contacts CLT1 has no immediate effect on operation, since the make contacts 1BH1 in series therewith are open.

It will be recalled that at 11:15 a.m. the one-half hour clock 1BH operates its make contacts 1BH1 and its break contacts 1BH2. Opening of the contacts 1BH2 has no immediate effect on operation, since the notching timing relay CLT has a substantial delay in dropout. The delay may be provided in any suitable manner, as by connecting a resistor R9 across the relay coil. The time delay in dropout is selected to be sufficient to permit certain operations to occur prior to such dropout, as will be apparent from the following discussion.

Closure of the make contacts 1BH1 results in energization of the notching relay 61 through the following circuit:

L1, 62—1, CLT1, 1BH1, 62—3, 61, R8, L2A

The resistor R8 has a resistance of a value sufficient to limit current flowing through the relay 61 to a safe magnitude.

Opening of the break contacts 61—1 in the circuit of the special service master relay SLHO has no immediate effect on operation, since the break contacts NO4—4 in parallel therewith remain closed. Closure of the make contacts 61—2 also has no immediate effect on operation, since such closure merely establishes a short circuit around the notching relay 62, as follows:

61—2, 62—3, 1BH1, CLT1, 62—1

The make contacts 61—3 close to establish the following energizing circuit for the floor selection relay NO1:

L1, NO1, NO4—7, NO3—8, NO2—9, 61—3, L2A

Opening of the break contacts 61—4 and 61—7 and closure of the make contacts 61—5 have no immediate effect on circuit operation. The make contacts 61—6 close to establish a holding circuit for the floor selection relay NO1 through its now closed holding contacts NO1—8.

Turning now to the remaining contacts of the floor selection relay NO1, opening of its break contacts NO1—6 has no effect on operation, since the break contacts NO2—6 in parallel therewith remain closed. Closure of the make contacts NO1—7 has no immediate effect on operation, since the make contacts 61—3 in parallel therewith are closed, as aforementioned. Closure of the make contacts NO1—9 also has no effect on operation, since the break contacts in series therewith 61—4 now are open. Assuming that the break contacts CTX6 are

closed, closure of the make contacts NO1—10 results in pickup of the master car assigning relay CNR.

Closure of the make contacts CNR1 results in pickup of the individual car assigning relays SLHOB, BSLHOB and CSLHOB, since the respective break contacts of the floor selection relays in series therewith all remain closed at this time. Closure of the make contacts CNR2 initiates a timing operation of the timing relay CTA, while opening of the break contacts CNR3 interrupts the discharge circuit for the capacitor CA1.

After a time sufficient to insure the completion of the above sequence of operations, the notching timing relay CLT times out. Opening of the make contacts CLT1 removes the short circuit around the notching relay 62, which picks up through the following energizing circuit:

L1, 62, 61—2, 61, R8, L2A

It will be observed that the notching relay 61 remains energized in series with the notching relay 62. Opening of the break contacts 62—1, 62—3, and 62—6 and closure of the make contacts 62—2 and 62—4 have no immediate effect on operation. The make contacts 62—5 close to parallel the now closed make contacts 61—6, thus having no effect on operation.

As mentioned heretofore, the one-half hour clock 1BH operates to reopen its make contacts 1BH1 and to reclose its break contacts 1BH2 after a period of approximately two minutes from the respective closure and opening thereof. Thus, at 11:17 a.m. the make contacts 1BH1 open without immediately effecting operation, and the break contacts 1BH2 close to reenergize the notching timing relay CLT. (This two-minute period of operation of the contacts of the one-half hour clock 1BH may vary slightly depending upon conditions; but in any event, the length of the period should be sufficient to insure the foregoing sequence of operations before the contacts 1BH1 reopen and the contacts 1BH2 reclose). As a result of the pickup of the relay CLT, its make contacts CLT1 close but have no effect on operation, since the make contacts 1BH1 now are open. Thus, the floor selection relay NO1 remains picked up for the first assigned period of special service operation, that is, until 11:25 a.m., when the contacts of the one-half hour clock 1BH again operate to produce the following sequence of operations. The break contacts 1BH2 open to initiate the timing out of the notching timing relay CLT, and the make contacts 1BH1 close to establish the following short circuit around the notching relay 61:

61—2, 62—2, 1BH1, CLT1, 62—4

Thus, the notching relay 61, as a result of the short circuit therearound, drops out.

Closure of the break contacts 61—1 has no effect on operation, since the break contacts NO4—4 in parallel therewith also are closed. Opening of the make contacts 61—2 also has no effect on operation, since the notching relay 62 remains energized through the following holding circuit:

L1, 62, 62—2, 1BH1, CLT1, 62—4, R8, L2A

Opening of the make contacts 61—3 has no effect on operation for the reason that the make contacts NO1—7 now are closed. Closure of the break contacts 61—4 results in energization of the floor selection relay NO2 through the now closed contacts NO1—9 (closure of the contacts 61—4 has no effect on the floor selection relay NO4, since the make contacts NO3—10 in series therewith are open). Opening of the make contacts 61—5 has no immediate effect on operation. Opening of the make contacts 61—6 also has no effect on operation, since the make contacts 62—5 in parallel therewith now are closed. Closure of the break contacts 61—7 results in the establishment of a holding circuit for the floor selection relay NO2 through its make contacts NO2—10, since the relay NO2 now is picked up.

Turning now to operation of the remaining contacts of

the relay NO2, it will be observed that both of the break contacts NO1-6 and NO2-6 now are open to interrupt the holding circuit of the transfer relay CTX. Such interruption would result in dropout of the relay CTX if it be assumed that the relay was energized through its holding contacts CTX5. (Such dropout would result in the closure of the break contacts CTX6 to reenergize the master car assigning relay CNR through the now closed parallel make contacts NO1-10 and NO2-12). Opening of the break contacts NO2-7 has no effect on operation at this time, since the break contacts NO3-4 in parallel therewith remain closed.

Opening of the break contacts NO2-8 results in dropout of the car assigning relay CSLHOB for the elevator car C, assuming that the make contacts CNR1 are closed. The break contacts NO2-9 open to interrupt one of the holding circuits for the floor selection relay NO1, but the relay NO1 still is maintained energized through its remaining holding circuit comprising the make contacts NO1-8 and 62-5. The make contacts NO1-10 close to establish a holding circuit for the relay NO2 through the break contacts 61-7. (It will be recalled that the notching relay 61 now is dropped out.) Closure of the make contacts NO2-11 has no immediate effect on operation, since the make contacts 61-5 in series therewith now are open. As mentioned above, the make contacts NO2-12 close to parallel the still closed make contacts NO1-10, thus having no immediate effect on operation.

Next it will be assumed that sufficient time has elapsed for the notching timing relay CLT to drop out. Opening of the make contacts CLT1 results in interruption of the holding circuit for the notching relay 62. Thus, the relay 62 now drops out. Closure of the break contacts 62-1 and 62-3 and opening of the make contacts 62-2 and 62-4 have no immediate effect on operation, since the contacts CLT1 now are open. Opening of the make contacts 62-5 interrupts the remaining holding circuit for the floor selection relay NO1, and thus the relay NO1 drops out. The break contacts 62-6 close to parallel the already closed break contacts 61-7, thus having no effect on operation.

Dropout of the floor selection relay NO1 is accompanied by closure of its break contacts NO1-6 partially to reestablish the holding circuit for the transfer relay CTX (recalling that the break contacts NO2-6 in parallel with the contacts NO1-6 now are open). Opening of the make contacts NO1-7 has no effect on operation, since the break contacts NO2-9 in series therewith now are open. Opening of the make contacts NO1-8 also has no effect on operation, since the parallel make contacts 61-6 and 62-5 previously had opened to drop out the relay NO1. The make contacts NO1-9 open, but the floor selection relay NO2 remains energized and picked up through its holding circuit. The make contacts NO1-10 also open but have no effect on operation, since the make contacts NO2-12 in parallel therewith are closed at this time.

At 11:27 a.m. the one-half hour clock 1BH functions to open its make contacts 1BH1 without affecting circuit operation and to close its break contacts 1BH2, which results in energization of the notching timing relay CLT. Closure of the make contacts MLT1 has no effect on operation, since the contacts 1BH1 now are open. Thus, the floor selection relay NO2 remains picked up for the second assigned period of special service operation, that is, until 11:31 a.m., when the contacts of the one-half hour clock 1BH again operate, resulting in the following sequence of operations: The break contacts 1BH2 open to initiate the timing out of the notching timing relay CLT. The make contacts 1BH1 close to energize the notching relay 61 through the following circuit:

L1, 62-1, CLT1, 1BH1, 62-3, 61, R8, L2A

Pickup of the notching relay 61 is accompanied by the opening of its break contacts 61-1. Such opening,

however, has no effect on operation, since the break contacts NO4-4 in parallel therewith are closed in the holding circuit of the special service master relay SLHO. The make contacts 61-2 close to establish the following 5 short circuit around the notching relay 62:

61-2, 62-3, 1BH1, CLT1, 62-1

Thus, the relay 62 remains dropped out. The make contacts 61-3 close but have no effect on operation, since 10 the break contacts NO2-9 are now open. Opening of the break contacts 61-4 also has no effect on operation, since the floor selection relay NO2 remains picked up through its holding circuit. Closure of the make contacts 61-5 results in energization of the floor selection 15 relay NO3 through the now closed make contacts NO2-11. The make contacts 61-6 close to establish a holding circuit for the floor selection relay NO3 through the make contacts NO3-9, which close as a result of the pickup of the relay NO3. Closure of the contacts 61-6 20 has no effect on the operation of the floor selection relay NO1, however, since its make contacts NO1-8 are open. Opening of the break contacts 61-7 has no effect on operation, since the break contacts 62-6 in parallel therewith now are closed.

Opening of the break contacts NO3-4 results in interruption of the holding circuit for the transfer relay CTX, since the break contacts NO2-7 also are open at this time. Thus, such interruption would result in dropout of the relay CTX if the relay had been energized 30 through its holding contacts CTX5. Opening of the break contacts NO3-5 has no effect on operation, since the break contacts NO4-5 in parallel therewith are closed. Assuming that the make contacts CNR1 are closed, opening of the break contacts NO3-6 results in dropout of the 35 car assigning relay BSLHOB for the elevator car B. Opening of the break contacts NO3-7 has no immediate effect on operation, since the break contacts NO2-8 in series therewith are open, inasmuch as the floor selection relay NO2 at this time is picked up. Opening of the 40 break contacts NO3-8 has no immediate effect on operation, since the break contacts NO2-9 in series therewith are also open.

As heretofore observed, closure of the make contacts NO3-9 resulted in the establishment of a holding circuit for the relay NO3 through the now closed make contacts 45 61-6. Closure of the make contacts NO3-10 has no immediate effect on operation, since the break contacts 61-4 in series therewith now are open. The make contacts NO3-11 also close to parallel the already closed make contacts NO2-12, thus having no effect on circuit 50 operation at this time.

Assuming that the notching timing relay CLT now times out, opening of its make contacts CLT1 removes the short circuit around the notching relay 62. The relay 62, therefore, is energized through the following circuit:

L1, 62, 61-2, 61, R8, L2A

(Note that the notching relays 61 and 62 once again are energized in series.) The break contacts 62-1 and 60 62-3 open and the make contacts 62-2 and 62-4 close, but such operation has no immediate effect for the reason that the make contacts CLT1 now are open, as aforementioned. The make contacts 62-5 close to parallel the now closed make contacts 61-6, thus having no effect 65 on operation. The break contacts 62-6 open to interrupt the holding circuit for the floor selection relay NO2, since the break contacts 61-7 also are open at this time, and thus the relay NO2 drops out.

The break contacts NO2-7 close partially to reestablish 70 the holding circuit for the transfer relay CTX. (It will be recalled that the break contacts NO3-4 in parallel with the contacts NO2-7 now are open.) The break contacts NO2-8 close, but such closure has no effect on operation, since the break contacts NO3-7 in series therewith now are open. Thus, the car assigning relay

CSLHOB for the elevator car C remains dropped out. Closure of the break contacts NO2-9 also as no effect on operation, since the break contacts NO3-8 in series therewith now are open. Opening of the make contacts NO2-10 in the holding circuit of the floor selection relay NO2 has no immediate effect on operation, since the relay NO2 already is dropped out as a result of the opening of the parallel break contacts 61-7 and 62-6. The make contacts NO2-11 open, but such opening has no effect on operation, since the floor selection relay NO3 is maintained energized through its holding circuit. Opening of the make contacts NO2-12 also has no effect on operation, since the make contacts NO3-11 in parallel therewith now are closed.

At 11:33 a.m. the one-half hour clock 1BH functions to open its make contacts 1BH1 without affecting operation and to close its break contacts 1BH2, as a result of which the notching timing relay CLT is energized. Closure of the make contacts CLT1, however, has no effect on operation, since the make contacts 1BH1 in series therewith now are open. Thus, the floor selection relay NO3 remains picked up during the third assigned period of special service operation.

At 11:35 a.m. the contacts 1BH2 of the one-half hour clock 1BH open to initiate the timing out of the notching timing relay CLT. At this time the make contacts 1BH1 close to establish the following short circuit around the notching relay 61:

61-2, 62-2, 1BH1, CLT1, 62-4

Thus, the relay 61 drops out.

Closure of the break contacts 61-1 in the holding circuit of the special service master relay SLHO has no effect on operation, since the break contacts NO4-4 in parallel therewith also are closed. Opening of the make contacts 61-2 has no immediate effect on operation, since the notching relay 62 remains picked up through the following holding circuit:

L1, 62, 62-2, 1BH1, CLT1, 62-4, R8, L2A

Opening of the make contacts 61-3 has no effect on operation, since the floor selection relay NO1 is dropped out at this time. The break contacts 61-4 close to energize the floor selection relay NO4 through the now closed make contacts NO3-10. Opening of the make contacts 61-5 has no effect on operation, since the make contacts NO2-11 in series therewith already are open. The make contacts 61-6 open, but such opening has no effect on operation, since the make contacts 62-5 in parallel therewith still are closed. The break contacts 61-7 close to establish a holding circuit for the floor selection relay NO4 through its now closed make contacts NO4-8.

Opening of the break contacts NO4-4 in the holding circuit of the special service master relay SLHO has no immediate effect on operation, since the break contacts 61-1 in parallel therewith now are closed. The break contacts NO4-5 open to interrupt the holding circuit of the transfer relay CTX, since the break contacts NO3-5 also are open at this time. Thus, if the relay CTX had been picked up through its holding contacts CTX5, the interruption of its holding circuit would result in its dropout. Opening of the break contacts NO4-6 results in dropout of the car assigning relay SLHOB for the elevator car A, assuming that the make contacts CNR1 of the master car assigning relay CNR are in closed condition. Opening of the break contacts NO4-7 has no effect on operation, since the break contacts NO3-8 in series therewith still are open, inasmuch as the floor selection relay NO3 is energized at this time. As heretofore noted, closure of the make contacts NO4-8, results in the establishment of a holding circuit for the relay NO4 through the now closed break contacts 61-7. The make contacts NO4-9 close, but such closure has no immediate effect on operation, since the make contacts NO3-11 in parallel therewith still are closed.

It will be assumed that sufficient time has elapsed for the notching timing relay CLT to time out. Opening of the make contacts CLT1 interrupts the holding circuit for the notching relay 62, and thus the relay 62 drops out. Closure of the break contacts 62-1 and 62-3 and opening of the make contacts 62-2 and 62-4 have no effect on operation, since the contacts CLT1 now are open. The make contacts 62-5 open to interrupt the holding circuit for the floor selection relay NO3, and thus the relay NO3 drops out. Closure of the break contacts 62-6 has no effect on operation, since the break contacts 61-7 in parallel therewith already have closed as a result of the dropout of the notching relay 61.

Turning now to the contacts of the floor selection relay NO3, which has dropped out, the break contacts NO3-5 close partially to reestablish the holding circuit for the transfer relay CTX. (It will be recalled that the break contacts NO4-5 in parallel with the contacts NO3-5 now are open.) Assuming that the make contacts CNR1 are closed, the break contacts NO3-6 and NO3-7 close to pick up the car assigning relays BSLHOB and CSLHOB for the elevator cars B and C, respectively. Closure of the break contacts NO3-8 has no effect on the operation, since the break contacts NO4-7 in series therewith now are open. Opening of the make contacts NO3-9 has no effect on operation, since it will be recalled that the holding circuit for the floor selection relay NO3 already has been interrupted as a result of the opening of the make contacts 61-6 and 62-5. The make contacts NO3-10 open, but such opening has no effect on operation, since the floor selection relay NO4 is maintained energized through its holding circuit. Opening of the make contacts NO3-11 also has no effect on operation, since the make contacts NO4-9 in parallel therewith now are closed.

At 11:37 a.m. the make contacts 1BH1 of the one-half hour clock open without affecting operation, and the break contacts 1BH2 thereof close to energize the notching timing relay CLT. Closure of the make contacts CLT1, however, has no effect on operation, since the contacts 1BH1 now are open. Thus, the floor selection relay NO4 remains picked up for the fourth assigned period of special service operation.

At 11:42 a.m. the contacts of the one-half hour clock 1BH again operate, resulting in the following sequence of operations: The break contacts 1BH2 open to start the timing out of the notching timing relay CLT. The make contacts 1BH1 close to energize the notching relay 61 in the manner heretofore explained.

Pickup of the notching relay 61 results in the opening of its break contacts 61-1 to interrupt the holding circuit for the special service master relay SLHO. (It will be recalled that the make contacts 1BM1 of the master clock 1BM and the break contacts NO4-4 both are open at this time.) Thus, the relay SLHO drops out to open its holding contacts SLHO3 and to open its make contacts SLHO4. Opening of the contacts SLHO4 removes the connection of the bus L2A to the bus L2 and thus interrupts direct current energization of the special service circuits connected to the bus L2A. As a result thereof, the notching relay 61 and the floor selection relay NO4 both drop out to close their break contacts 61-1 and NO4-4, respectively, partially to reestablish the holding circuit for the special service master relay SLHO. It will be observed, therefore, that special service operation has terminated and that its reinitiation awaits the closure of the master clock make contacts 1BM1 on the following day, provided the manually-operable switch 163 is maintained in closed condition. Until that time, all four cars of the elevator system are transferred to and remain conditioned for normal off-peak operation.

The master load relay SWRX, is energized during special service operation through the break contacts CTX6 if at least one of the sets of make contacts SWR3,

BSWR3 or CSWR3 of the individual auxiliary load relays SWR, BSWR and CSWR for the elevator cars A, B and C, respectively, closes to indicate that its associated elevator car is loaded and is about to leave an assigned floor. Pickup of the relay SWRX results in closure of its make contacts, SWRX1 partially to complete an energizing circuit for the master car assigning relay CTX and SWRX2 to establish a holding circuit for the relay SWRX.

OFF-PEAK OPERATION

In order to assure a full understanding of the invention, certain typical operation of the elevator system now will be considered. First, it will be assumed that the entire system is conditioned for off-peak operation, that the elevator cars all are parked at the lower terminal floor and that a passenger enters the elevator car A at the lower terminal floor for the purpose of proceeding to the fifth floor.

The doors of the elevator cars may be of the manually-opened, spring-closed type or may be of conventional power-operated design. Upon entering the elevator car A, the passenger presses the car call push button 5c (FIG. 2) to energize the associated car call registering relay 5CR. This relay closes its make contacts 5CR1 to establish a holding circuit around the push button. The relay also closes its make contacts 5CR2; but such closure has no effect on operation, since the make contacts SLHO1 of the special service master relay SLHO are open, inasmuch as the elevator system is not conditioned for special service operation. Opening of the break contacts 5CR3 (FIG. 4) results in deenergization of the call relay 78. Consequently, the break contacts 78—1 close to energize the dispatching relay 80N as follows:

SLHT1—W5T2—NOX3—SCCO12 in parallel
78—1, SCCO10, 80N, L2

(Note that the first four sets of contacts in the foregoing circuit all are closed, since the car A is not conditioned for special service operation.)

Inasmuch as the relay 80N now is picked up, the contacts 80N1 (FIG. 1) are closed. Since the elevator car A is at the lower terminal floor, it will be understood that the up preference relay W (FIG. 1) is energized and picked up to close its make contacts W1. It will be assumed also that the car A has remained at the lower terminal floor for a time sufficient to result in closure of the break contacts 70T1. Consequently, upon closure of the doors, the door relay DR closes its make contacts DR1 to complete the following circuit:

L1, 80N1, 70T1, W1, F1, 21, U, M, DR1, L2

Upon energization, the up switch U closes its make contacts U1 to release the elevator brake. Contacts U2 and U3 close to energize the generator field winding 17F with proper polarity for up travel of the elevator car. Contacts U4 closes to complete the following energizing circuit for the speed relay V:

L1, U4, 19, E1, V, L2

The speed relay closes its make contacts V1 to shunt the resistor R1 and thus conditions the elevator car for full speed operation. The speed relay V also opens its break contacts V2 (FIG. 3) without immediate effect on system operation.

Continuing with the operation of the up switch U, the energized up switch closes its make contacts U5 to establish a holding circuit around the contacts 80N1, 70T1 and W1. Break contacts U6 open to prevent energization therethrough of the down preference relay X.

The elevator car A now accelerates in the up direction for the purpose of carrying the passenger to the fifth floor.

It will be recalled that the running relay M also was energized. As a result of its energization, the running

relay closes its make contacts M1 to prepare the relays G, E and F for subsequent energization. The make contacts M2 close without affecting operation, since the break contacts J1 in parallel therewith remain closed at all times during off-peak operation of the car A. Make contacts M3 close to energize the non-interference relay 70T.

The non-interference relay opens its break contacts 70T1, 70T3 (FIG. 4) and 70T4 and closes its make contacts 70T2 (FIG. 3) and 70T5 (FIG. 4), but such contact operations have no immediate effect on the operation of the system.

Under the assumed conditions, opening of the break contacts M4 (FIG. 1) has no immediate effect on system operation. Referring to FIG. 2, the running relay M also closes its make contacts M5 and opens its break contacts M6. Such contact operations have no immediate effect on the operation of the system.

As the elevator car nears the fifth floor, the brush kk (FIG. 4) engages the contact segment k5, which is positioned above the now open break contacts 5CR3. Consequently, the call-above relay 78U is energized through the circuit:

L1, 6CR3, 6DR2, 5UR2, k5, kk, W8, 78U, L2

25 The relay 78U closes its make contacts 78U1 (FIG. 1). Under the assumed conditions, such closure has no effect on the operation of the system for the reason that the make contacts SLHOB1 are open.

However, the approach of the elevator car A toward 30 the fifth floor brings the brush bb (FIG. 2) into engagement with the contact segment b5 to energize the car call stopping relay T through the circuit:

L1, 5CR1, b5, bb, W4, T, M5 L2

35 The car call stopping relay closes its make contacts T1 (FIG. 1) to energize through the contacts M1 the three relays G, E and F in parallel. The relay G closes its make contacts G1 to establish a holding circuit around the contacts T1.

40 The energization of the inductor slowdown and stopping relays E and F prepares these relays for subsequent operation. As the elevator car A nears the fifth floor, the inductor slowdown relay E reaches the inductor plate UEP for the fifth floor, which completes a magnetic circuit resulting in the opening of the normally-closed contacts E1. Such opening deenergizes the speed relay V. As a result of the deenergization of the speed relay V, make contacts V1 open to introduce the resistor R1 in series with the generator field winding 17F. The resulting decrease in the output of the generator slows the elevator car A to a landing speed. Closing of break contacts V2 (FIG. 3) has no immediate effect on the system.

45 As the elevator car A slowly approaches the fifth floor, the stopping relay F (FIG. 1) reaches the inductor plate UFP for the fifth floor. This completes a magnetic circuit which results in the opening of the normally-closed contacts F1. In opening, the contacts F1 deenergize the up switch U and the running relay M.

50 The up switch U now opens its make contacts U1 to apply the elevator brake. Contacts U2 and U3 open to deenergize the generator field winding. Consequently, the elevator car now stops accurately at the fifth floor and its doors open to permit the departure of the passenger who registered the car call for the fifth floor. Opening of the make contacts U4 and U5 and closure of the break contacts U6 have no immediate effect on the operation of the system.

55 The running relay M opens its make contacts M1 to deenergize the relays G, E and F. The relay G opens its make contacts G1. Opening of the make contacts M2 has no immediate effect on system operation. Make contacts M3 open to deenergize the non-interference relay 70T. This relay now starts to time out. Closure of the break contacts M4 and opening of the make contacts M5 (FIG. 2) have no immediate effect on system operation.

60 Referring to FIG. 2, it should be noted that as the

elevator car A approached the fifth floor, the brush *dd* engaged the contact segment *d5*. When the running relay dropped out to close its break contacts *M6*, the following cancelling circuit was completed:

L1, 5CR1, 5CRN, *d5*, *dd*, W5, M6 L2

Consequently, the car call registering relay 5CR is reset. As the car came to a stop, the brush *bb* passed slightly above the associated contact segment *b5*.

The setting of the call registering relay 5CR opens the make contacts 5CR1 and 5CR2 without affecting operation. In addition, the break contacts 5CR3 (FIG. 4) reclose to complete an energizing circuit for the call relay 78.

The call relay 78 as a result of its energization opens its break contacts 78-1 to drop out the dispatching relay 80N. As a result thereof, the make contacts 80N1 (FIG. 1) open. Consequently, when the non-interference relay 70T times out and recloses its break contacts 70T1, the up switch *U* and the running relay *M* cannot be energized until a call is registered from one of the floors or in the elevator car A to close the contacts 78-1 to reenergize the relay 80N.

Next it will be assumed that as the elevator car A was leaving the first floor in the preceding example, a prospective passenger at the second floor registered an up floor call by operation of the up floor call push button 2U (FIG. 3). Such operation energizes the up floor call registering relay 2UR, which closes its contacts 2UR1 to establish a holding circuit around the push button. In addition, the registering relay opens its break contacts 2UR2 in the call circuit 30 (FIG. 4) and similar contacts, such as the contacts 2UR3 in the call circuit B30 for the elevator car B, for the remaining elevator cars in the bank. Since the registration of the car call for the fifth floor in the elevator car A already has deenergized the relay 78, opening of the contacts 2UR2 has no effect thereon. However, the opening of the remaining contacts of the relay 2UR may affect the remaining elevator cars of the system. For example, the opening of the break contacts 2UR3 deenergizes the relay B78 for the car B and permits operation of this elevator car. The present discussion, however, will be confined to the elevator car A.

As the elevator car A nears the second floor, the brush *ee* (FIG. 3) engages the contact segment *e2* to establish the circuit:

L1, 2UR1, *e2*, *ee*, W6, S, SLHOB2, L2

The energization of the floor call stopping relay *S* results in closure of the make contacts *S1* (FIG. 1) to energize the relays *G*, *E* and *F*. These cooperate to stop the elevator car A at the second floor by a sequence which will be clear from the preceding discussion of the stopping of the elevator car at the fifth floor. As the elevator car stops, the engagement of the brush *ff* (FIG. 3) with the contact segment *f2* and the closure of the break contacts *V2* complete the following cancelling circuit:

L1, 2UR1, 2URN, *f2*, *ff*, W7, SLHOB3, V2, L2

This resets the up floor call registering relay 2UR in the manner previously described. As a result of this resetting, the relay opens its contacts 2UR1 to remove the holding circuit around the push button 2U and recloses its break contacts 2UR2 (FIG. 4). Inasmuch as the contacts 5CR3 remain open, the reclosure of the contacts 2UR2 has no immediate effect on the system. However, the relay also recloses its break contacts 2UR3. If no other call is registered affecting the elevator car B, the reclosure of the contacts 2UR3 results in energization of the call relay B78.

Next it will be assumed that a prospective passenger at the fourth floor registers a down floor call by operation of the push button 4D (FIG. 3) after the elevator car A reached the fifth floor. The resultant energization

of the down floor call registering relay 4DR closes the make contacts 4DR1 to establish a holding circuit around the push button. In addition, the registering relay opens its break contacts 4DR2 (FIG. 4) and similar contacts 5 for the remaining cars, such as the contacts 4DR3 for the elevator car B. The opening of the break contacts 4DR2 deenergizes the call relay 78. This relay recloses its break contacts 78-1 to energize the dispatching relay 80N in the manner heretofore described. As a result, the make contacts 80N1 (FIG. 1) close.

It will be assumed that the elevator car A has remained at the fifth floor for time sufficient to permit reclosure of the break contacts 70T1 of the non-interference relay. Consequently, upon closure of the doors associated with the car A, the up switch *U* and the running relay *M* are energized in the manner previously described to move the car upwardly to the upper terminal or sixth floor. As the elevator car A nears the upper terminal floor, the brush *ee* (FIG. 3) engages the contact segment *e6* to complete the following energizing circuit:

L1, *e6*, *ee*, W6, S, SLHOB2, L2

The relay *S* closes its make contacts *S1* (FIG. 1) to energize the relays *G*, *E* and *F*. These relays initiate a stopping operation of the elevator car A at the sixth floor in the manner which will be clear from the earlier discussion of the stopping of the elevator car at the fifth floor. As it reaches the sixth floor, the elevator car A opens its limit switch 23 to deenergize the up preference relay *W*. Since this relay closes its break contacts *W2* and since the break contacts *U6* close as the car stops, an energizing circuit is completed for the down preference relay *X* through the limit switch 24. The deenergization of the up preference relay and the energization of the down preference relay condition the elevator car A for down travel.

As the car A approached the sixth floor, the brush *kk* (FIG. 4) engaged the contact segment *k6* to reenergize the call-above relay 78U. Such energization, however, had no effect on operation for reasons which will be apparent from the preceding discussion of the stopping of the elevator car at the fifth floor.

After the expiration of time sufficient to permit the non-interference relay 70T (FIG. 1) to time out, the break contacts 70T1 close to complete the following circuit:

L1, 80N1, 70T1, X1, F2, 22, D, M, DR1, L2

The relay *D* upon energization closes its make contacts 50 D1 to release the elevator brake. Contacts *D2* and *D3* close to energize the generator field winding 17F with proper polarity for down travel. Contacts *D4* close to complete through the limit switch 20 and the contacts *E2*, an energizing circuit for the speed relay *V*. This relay closes its make contacts *V1* to shunt the resistor *R1*. The elevator car A now accelerates to its full speed in the down direction.

Closure of the make contacts *D5* establishes a holding circuit around the contacts 80N1, 70T1 and *X1*. 60 Opening of the break contacts *D6* has no immediate effect on the operation of the system. The running relay *M* upon energization operates its contacts in the manner previously described.

As the elevator car A nears the fourth floor, the brush *gg* (FIGS. 3) engages the contact segment *g4* to complete the following energizing circuit:

L1, 4DR1, *g4*, *gg*, X6, S, SLHOB2, L2

As a result of its energization, the floor call stopping relay *S* closes its make contacts *S1* (FIG. 1) to energize the relay *G*, *E* and *F*. The relay *G* closes its make contacts *G1* to establish a holding circuit around the contacts *S1*. The continued movement of the elevator car A brings the inductor slowdown relay *E* adjacent the inductor plate *DEP* for the fourth floor and completes

a magnetic circuit resulting in opening of the contacts E2. Such opening results in deenergization of the speed relay V and this relay closes its break contacts V2 (FIG. 3) and opens its make contacts V1 (FIG. 1) to introduce the resistor R1 in series with the generator field winding.

The decrease in energization of the field winding slows the elevator car to a landing speed. The continued movement of the elevator car A at a slow speed brings the inductor stopping relay F adjacent the inductor plate DFP to open the contacts F2. Such opening deenergizes the down switch D and the running relay M. The down switch D opens its make contacts D1 to apply the elevator brake. Contacts D2 and D3 open to deenergize the generator field winding, and the elevator car stops accurately at the fourth floor. Opening of make contacts D4 and D5 and closure of break contacts D6 have no immediate effect on the operation of the system.

During the stopping operation, the brush hh (FIG. 3) engages the contact segment h4 to complete the following cancelling circuit:

L1, 4DR1, 4DRN, h4, hh, 70T2, SLHOB3, V2, L2

In addition, the brush jj engages the contact segment j4 to complete a second cancelling circuit as follows:

L1, 4DR1, 4DRN, NO2-3 and CTX3 in parallel, j4, jj, X7, SLHOB3, V2, L2

In resetting, the relay 4DR opens its holding contacts 4DR1. In addition, the relay recloses its break contacts 4DR2 (FIG. 4) and corresponding contacts in the call circuits for the remaining elevator cars of the system. If no other call is registered affecting the call circuit 30, the call relay 78 is energized and prevents further operation of the elevator car A.

It will be assumed that the passenger at the fourth floor enters the elevator car and operates the push button 1c (FIG. 2) to initiate movement of the elevator car to the first floor. The resultant energization of the car call registering relay 1CR closes the holding contacts 1CR1 and the make contacts 1CR2. Closure of the contacts 1CR2 has no immediate effect on system operation under the assumed conditions. Opening of the break contacts 1CR3 (FIG. 4) deenergizes the call relay 78 and this relay closes its break contacts 78-1 to permit further movement of the elevator car. If sufficient time has elapsed for the non-interference relay 70T to drop out, the break contacts 70T1 (FIG. 1) close. If the doors also are closed, an energizing circuit again is completed for the down switch D and running relay M through the now closed make contacts 80N1. These cooperate in the manner previously discussed to move the elevator car toward the first floor.

Opening of the make contacts 70T2 (FIG. 3) while the elevator car still was at the fourth floor had no immediate effect on operation for the reason that the brush jj remained in engagement with the contact segment j4 in the aforementioned fourth floor down floor call cancelling circuit until the elevator car A left the fourth floor.

As the elevator car nears the first floor, the brush aa (FIG. 2) engages the contact segment a1 to complete an energizing circuit for the car call stopping relay T. This relay closes its make contacts T1 (FIG. 1) to energize the relays G, E and F through the contacts M1. The energized relays E and F cooperate in the manner previously described to stop the elevator car at the first floor.

As it reaches the lower terminal floor, the elevator car A opens the limit switch 24 to deenergize the down preference relay X. This relay closes its break contacts X2 to complete an energizing circuit for the up preference relay W as the elevator car stops at the lower terminal floor. The deenergization of the down preference relay X and the energization of the up preference relay W condition the elevator car A for up travel.

Pickup of the up preference relay W is accompanied by closure of its make contacts W5 (FIG. 2). Thus, as

the elevator car stops, the brush dd engages the contact d1 to complete the following cancelling circuit:

L1, 1CR1, 1CRN, d1, dd, W5, M6, L2

5 In resetting, the relay 1CR opens its holding contacts 1CR1 and its make contacts 1CR2. The break contacts 1CR3 (FIG. 4) close to complete an energizing circuit for the call relay 78. The relay 78 opens its break contacts 78-1 to prevent further operation of the elevator car A until a call is registered requiring such operation.

10 The elevator system as thus far described has provided what may be termed off-peak operation, that is, balanced service in the two directions of travel between the upper and lower terminal floors of the building.

SPECIAL SERVICE OPERATION

It now will be assumed that the four elevator cars of the system A, B, C and D are parked at the lower terminal floor conditioned for up travel and that no call for service is registered in the system. Referring to FIG. 5,

20 at 11:14 a.m. the make contacts 1BM1 of the master clock 1BM close to energize the special service master relay SLHO, assuming that the manually-operable switch 103 is in closed condition. Closure of the make contacts SLHO1 and SLHO2 (FIG. 2) and similar contacts for the elevator car C has no immediate effect on operation, since under the assumed conditions no car call is registered in the system. Closure of the make contacts SLHO3 (FIG. 5) completes a holding circuit for the relay SLHO in order to maintain this relay energized after the subsequent opening of the master clock contacts 1BM1. Closure of the make contacts SLHO4 connects the bus L2A to the bus L2 to provide direct-current energization for the circuits connected to the bus L2A.

30 At 11:15 a.m. the one-half hour clock contacts 1BH1 and 1BH2 close and open, respectively, to effect the energization of the floor selection relay NO1 by a sequence of operations which will be apparent from the preceding discussion of FIG. 5.

35 Closure of the make contacts NO1-10 results in energization of the master car assigning relay CNR through the break contacts CTX6. The make contacts CNR1 close to energize the car assigning relays SLHOB, BSLHOB and CSLHOB for the elevator cars A, B and C, respectively. The make contacts CNR2 close to initiate a timing operation of the timing relay CTA by permitting the capacitor CA1 to charge therethrough, while the break contacts CNR3 open to interrupt the discharge path of the capacitor CA1.

40 Referring now to FIG. 4, pickup of the car assigning relays is accompanied by closure of their respective make contacts SLHOB8, BSLHOB8 and similar contacts for the elevator car C. Assuming that the non-interference relay 70T (FIG. 1) has timed out and recalling that no car call is registered for the elevator car A, the no car call relay SCCO (FIG. 4) is energized through the following circuit:

L1, 70T3, 50-1, SCCO, SLHOB8, L2

45 Consequently, the relay SCCO picks up to close its make contacts SCCO9 to establish a holding circuit for the relay.

Inasmuch as the car A is at the first floor, the brush mm is not in engagement with any of its associated contact segments, and the assigned floor relay NOX, therefore, remains dropped out. The dispatching timing relay SLHT is energized through the now closed make contacts 70T5 and SLHOB8. Opening of the make contacts SLHT1 prevents energization therethrough of the dispatching relay 80N. The load relay W5T, through the 50 closed load weighing switch WH, also is energized and picked up. Opening of the break contacts W5T1 and W5T2 prevents energization therethrough of the auxiliary load relay SWR and the dispatching relay 80N, respectively.

55 Closure of the make contacts SLHOB9 connects the

signs 101 for energization from the buses L1 and L2. These signs indicate that the elevator car A is incapable of providing up service.

Returning to the contacts of the no car call relay SCCO, opening of the break contacts SCCO10 and SCCO12 prevents energization therethrough of the dispatching relay 80N. Since the reversing relay J is dropped out, closure of the make contacts SCCO11 completes the following energizing circuit for the dispatching relay:

L1, NOX3, J3, SCCO11, 80N, L2

Referring to FIG. 1 and assuming that the doors associated with the elevator car A are closed and consequently that the door relay DR is picked up to close its make contacts DR1, closure of the make contacts 80N1 completes an energizing circuit for the up switch U and the running relay M. The elevator car A consequently accelerates to full speed in the up direction.

It will be observed by inspection of FIG. 1 that when the car assigning relay SLHOB for the elevator car A was energized, its make contacts SLHOB1 closed to prepare the reversing relay J for subsequent energization.

By inspection of FIGS. 4 and 1, it will be noted that the elevator car B also is accelerated to full speed in the up direction in a manner similar to that described for the car A. Although control circuits are not shown in FIGS. 4 and 1 for the elevator car C, it is assumed that the car C also is provided with circuits which cause its acceleration in the up direction at this time. Since the car D is not conditioned for special service operation, it remains at the first floor.

In order to expedite service to the assigned floors during special service operation, assigned elevator cars preferably are prevented from answering registered up or down floor calls. To this end, the break contacts SLHOB2 and SLHOB3 (FIG. 3) of the car assigning relay SLHOB opened when this relay was energized to prevent, respectively, energization of the floor call stopping relay S and cancellation of registered floor calls during up and down travel of the car A. Similar contacts, such as the contacts BSLHOB2 and BSLHOB3 for the car B, are provided in the floor call registering relay circuits for the cars B and C. In order further to expedite service for assigned floors, it is desirable that the break contacts of the floor call registering relays in the call circuit 30 (FIG. 4) be shunted during up and down travel of the car A. To this end, the make contacts SLHOB4 through SLHOB7 of the car assigning relay SLHOB close to shunt the break contacts of the floor call registering relays for floors above the first floor in the call circuit 30. As is shown, similar contacts also are provided for the elevator car B, and the call circuit for the car C (not shown) also is provided with such contacts.

Referring now to FIG. 2 and confining the following discussion primarily to the elevator car A, it will be observed that the no car call relay SCCO, in picking up, opened its break contacts SCCO2, SCCO3, SCCO5, and SCCO7 in the car A car call registering circuits for the sixth, fifth, fourth and third floors, respectively. Thus the pushbuttons for these floors are rendered ineffective for registering car calls as long as the relay SCCO remains energized. Opening of the break contacts SCCO8 prevents the registration therethrough of car calls for the second floor by operation of the pushbutton 2C. However, since the break contacts W3 in parallel with the contacts SCCO8 are open only when the up preference relay W is energized, i.e., when the car A is conditioned for up travel, car calls for the second floor may be registered when the car A is conditioned for down travel, inasmuch as the contacts W3 then are closed.

Closure of the make contacts SCCO4 and SCCO6 has no effect on operation at this time for the reason that the make contacts NO2-1 and NO3-1 respectively in series therewith are open. Since the floor selection relay

NO1 is energized and its make contacts NO1-1, therefore, are closed, closure of the make contacts SCCO1 results in the registration of what may be termed an "artificial" car call for the sixth floor. Thus, the elevator car A proceeds upwardly in the manner previously described to answer such artificial car call. (It will be noted that an artificial car call also is registered for the sixth floor for the car B by operation of the make contacts BSCCO1 and NO1-2. Similar contacts (not shown) are provided in the sixth floor car call circuit for the car C.)

As the elevator car nears the sixth floor, the brush bb engages the contact segment b6 to complete the following energizing circuit for the car call stopping relay T:

L1, SCCO1, NO1-1, b6, bb, W4, T, M5, L2

Energization of the relay T results in closure of its make contacts T1 (FIG. 1) to energize the relays G, E and F. These cooperate to stop the elevator car A at the sixth floor by a sequence which will be clear from the preceding discussion.

As the elevator car stops, engagement of the brush cc with the contact segment c6 has no effect on operation for the reason that the make contacts 6CR1 are open, since the elevator car proceeded to the sixth floor in response to an artificial car call, as aforementioned, rather than in response to the registration of a car call by the car call registering relay 6CR.

As the car A neared the sixth floor, the brush kk (FIG. 4) engaged the contact segment k6 to complete the following energizing circuit for the call-above relay 78U:

L1, k6, kk, W8, 78U, L2

As a result of this energization, the call above relay 35 closed its make contacts 78U1 (FIG. 1) to complete an energizing circuit for the reversing relay J as follows:

L1, 78U1, SLHOB1, X3, J, L2

Opening of the break contacts J1 prevents subsequent energization therethrough of the up preference relay W. (It will be recalled that the limit switch 23 is opened upon arrival of the car A at the sixth floor to drop out the relay W in any event.) Closure of the make contacts J2 establishes a holding circuit for the relay J, which is maintained through the break contacts M4 as the elevator car stops at the sixth floor and the running relay M drops out, although the break contacts X3 in parallel with the contacts M4 subsequently open. Opening of the break contacts J3 (FIG. 4) prevents subsequent energization therethrough of the dispatching relay 80N. Closure of the make contacts J4 prepares the dispatching relay for subsequent energization therethrough as hereinafter will be described.

Thus, the elevator car A now is stopped at the sixth floor conditioned for down travel. (It will be recalled that dropout of the up switch U (FIG. 1) and up preference relay W results in closure of the break contacts U6 and W2, respectively, to energize the down preference relay X through the limit switch 24.) At approximately 55 the same time, the cars B and C arrive at the sixth floor and are conditioned for down travel by a sequence of operations which will be apparent from the preceding discussion of the arrival of the car A at the sixth floor. It will be noted that the cars A, B and C have traveled to 60 the sixth floor in the absence of the registration of a floor call or a car call but in response to the registration of an artificial car call, as aforementioned. The stopping of the cars is accompanied by the opening of their respective doors to permit the entry therethrough of passengers desiring down elevator service.

It now will be assumed that sufficient time has elapsed for the non-interference relay 70T (FIG. 1) to drop out. Closure of the break contacts 70T1, opening of the make contacts 70T2 (FIG. 3) and closure of the break contacts 70T3 (FIG. 4) have no immediate effect on opera-

tion. Opening of the make contacts **70T5** initiates the timing out of the dispatching timing relay **SLHT**. (It will be recalled that the relay **SLHT** has a 15 second time delay in drop out.)

When the car A arrived at the sixth floor, the brush *mm* engaged the contact segment *m6* to complete the following energizing circuit for the assigned floor relay **NOX**:

L1, NO1-4, m6, mm, NOX, SLHOB8, L2

Pickup of the relay **NOX** is accompanied by closure of its make contacts **NOX1** to establish a holding circuit for the relay when the non-interference relay **70T** times out to close its break contacts **70T4**. Closure of the make contacts **NOX2** and opening of the break contacts **NOX3** have no immediate effect on operation.

It next will be assumed that at least one car, for example the car A, is loaded at the sixth floor sufficiently to open the load switch **WH** to interrupt the energizing circuit for the load relay **W5T** before the 15 second time delay in drop out of the dispatching timing relay **SLHT** expires. At the expiration of its one-second time delay in dropout, the relay **W5T** drops out to close its break contacts **W5T1**. When the doors associated with the elevator car A close, the make contacts **DR2** close to complete the following energizing circuit for the auxiliary load relay **SWR**:

L1, NOX2, W5T1, DR2, SWR, SLHOB8, L2

Pickup of the relay **SWR** is accompanied by the opening of its break contacts **SWR1** (FIG. 5) to interrupt the charging circuit for the capacitor **CA1** and to prevent subsequent energization therethrough of the timing relay **CTA**. (It will be recalled that the relay **CTA** has a 90 second time delay in pickup and that under the assumed conditions such 90 second period has not yet expired.) Closure of the make contacts **SWR2** completes a discharge path for the capacitor **CA1** through the resistor **R5**. Closure of the make contacts **SWR3** completes an energizing circuit for the master load relay **SWRX** through the break contacts **CTX6**.

In picking up, the relay **SWRX** closes its make contacts **SWRX1** to prepare the transfer relay **CTX** for subsequent energization therethrough. Closure of the make contacts **SWRX2** establishes a holding circuit for the relay **SWRX**.

Returning now to the operation of the load relay **W5T** (FIG. 4), dropout of this relay was accompanied by closure of its break contacts **W5T2** to complete an energizing circuit for the dispatching relay **80N** through the now closed make contacts **J4**. Such energization results in closure of the make contacts **80N1** (FIG. 1) to energize the down switch **D** and the running relay **M**. Thus, the car A accelerates to full speed from the sixth floor in the down direction.

In picking up, the running relay closes its make contacts **M3** to pick up the non-interference relay **70T**. Opening of the break contacts **M4** interrupts the holding circuit for the reversing relay **J**, inasmuch as the break contacts **X3** also are open as a result of the energization of the down preference relay **X**, and the relay **J** drops out. Such dropout, however, has no immediate effect on operation.

As the car A leaves the sixth floor, the brush *mm* (FIG. 4) disengages the contact segment *m6* to drop out the assigned floor relay **NOX**. Opening of the make contacts **NOX1** in the holding circuit of the relay **NOX** has no immediate effect on operation. Opening of the make contacts **NOX2** results in dropout of the auxiliary load relay **SWR**. This relay closes its break contacts **SWR1** (FIG. 5) and opens its make contacts **SWR2** to reinitiate a timing operation of the timing relay **CTA** (assuming that the auxiliary load relays for the cars B and C also are deenergized at this time). Opening of the make contacts **SWR3** has no effect on operation, since the master load relay **SWRX** remains energized through its holding circuit.

Returning to FIG. 4, the assigned floor relay **NOX**, in dropping out, closes its break contacts **NOX3**, but such closure had no immediate effect on operation for the reason that the break contacts **W5T2** in parallel therewith remain closed.

It will be assumed that a passenger who entered the car A at the sixth floor registered a car call for the second floor through the now closed break contacts **W3** (FIG. 2) by pressing the car call pushbutton **2c**. (It is assumed in the present embodiment of the invention that the cafeteria for the building served by the elevator system is located on the second floor.) In response to the registration of such car call, the elevator car A stops at the second floor by a sequence of operations which will be apparent from the preceding discussion.

If a sufficient number of passengers depart the car A at the second floor to close the load weighing switch **WH** (FIG. 4), such closure results in energization of the load relay **W5T**. Opening of the break contacts **W5T1** has no immediate effect on operation. Opening of the break contacts **W5T2** also has no effect on operation, since it will be recalled that the break contacts **NOX3** in parallel therewith closed as the car A left the sixth floor. Thus, the dispatching relay **80N** remains energized and picked up through the now closed contacts **J3** and **SCCO11**.

After the expiration of time sufficient to permit the unloading of the car A at the second floor, the non-interference relay **70T** (FIG. 1) drops out to close its break contacts **70T1**. Subsequently, the doors associated with the car close to effect completion of the energizing circuit for the down switch **U** and the running relay **M**. The car A thus accelerates to full speed in the down direction. As the car approaches the first floor, the brush *aa* (FIG. 2) engages the contact segment *a1* to energize the car call stopping relay **T**. Closure of the make contacts **T1** (FIG. 1) results in the stopping of the car at the first floor by a sequence of operations which will be apparent from the foregoing discussion.

In the preceding example, it will be noted that the car **A** proceeded from the second floor to the first floor although no car call was registered for the first floor. If it be assumed that a passenger who entered the car A at the sixth floor registered a car call for the first floor by pressing the car call pushbutton **1c** (FIG. 2), such registration would have had no additional effect on the operation of the car A, since the car proceeds from the second floor to the first floor in any event by operation of the contacts **J3** and **SCCO11** (FIG. 4), as aforementioned.

By inspection of the drawings and with reference to the preceding discussion of operation of the car A, it will be appreciated that the cars **B** and **C** operate in a similar manner to expedite traffic from the sixth floor to the second and first floors. After the expiration of time sufficient to permit their respective non-interference relays to time out and the closure of the doors respectively associated with the elevator cars **A**, **B** and **C**, each of these cars again travels to the sixth floor for the purpose of carrying additional passengers therefrom to the second and first floors by a sequence which will be apparent from the preceding discussion of the car A.

Let it be assumed that while the elevator system is conditioned for off-peak operation immediately prior to the initiation of special service operation at 11:15 a.m., a passenger enters the car A at the lower terminal or first floor and presses the car call pushbutton **5c** (FIG. 2) to energize the associated car call registering relay **5CR**, thereby registering a car call for the fifth floor. Such registration results in closure of the make contacts **5CR2**. It will be recalled that at 11:14 a.m. the special service master relay **SLHO** (FIG. 5) was energized to close its break contacts **SLHO1** (FIG. 2). Thus, closure of the contacts **5CR2** results in energization of the car call relay **50**. Opening of the break contacts **50-1** (FIG. 4) prevents energization therethrough of the no car call relay **SCCO**.

Referring now to FIG. 2, it will be observed that the

make contacts **SCCO1** remain open to prevent the registration of the artificial car call for the sixth floor upon closure of the make contacts **NO1-1** at 11:15 a.m. Inasmuch as the registration of the car call for the fifth floor resulted in the opening of the break contacts **5CR3** (FIG. 4) in the call circuit **30** for the car A, the energizing circuit for the call relay **78** is interrupted and this relay drops out. The relay **78** closes its break contacts **78-1** to energize the dispatching relay **80N** through the still closed break contacts **SCCO10**. As a result thereof, the make contacts **80N1** (FIG. 1) close. If sufficient time has elapsed for the non-interference relay **70T** to drop out, the break contacts **70T1** close. If the doors associated with the car A also are closed the energizing circuit is completed for the up switch **U** and the running relay **M**. These cooperate in the manner previously discussed to move the elevator car toward the fifth floor.

As the car approaches the fifth floor, the brush **bb** (FIG. 2) engages the contact segment **b5** to complete the following energizing circuit for the car call stopping relay **T**:

L1, 5CR1, b5, bb, W4, T, M5, L2

The relay **T** closes its make contacts **T1** (FIG. 1) to energize the relays **G**, **E** and **F** through the contacts **M1**. The energized relays **E** and **F** cooperate in the manner previously described to stop the car A at the fifth floor. As the car stops at the fifth floor, the brush **dd** (FIG. 2) engages the contact segment **d5** to cancel the fifth floor car call.

Opening of the make contacts **5CR2** results in dropout of the car call relay **50**, while closure of the break contacts **5CR3** (FIG. 4) completes an energizing circuit for the call relay **78**. It will be noted that the call-above relay **78U** picked up when the brush **kk** engaged the contact segment **k5**. Opening of the break contacts **78-1** prevents subsequent energization therethrough of the dispatching relay **80N**. Closure of the make contacts **78U1** (FIG. 1) results in energization of the reversing relay **J**, which, in turn, opens its break contacts **J1** to deenergize the up preference relay **W**. Closure of the break contacts **W2** results in pickup of the down preference relay **X** to condition the car A for down travel. When the relay **J** picked up, it opened its break contacts **J3** (FIG. 4) and closed its make contacts **J4**, resulting in energization of the dispatching relay **80N**. Upon expiration of the non-interference time, the relay **70T** (FIG. 1) drops out to close its break contacts **70T1** to energize the relays **D** and **M** when the make contacts **DR1** of the door relay close. Thus, the car A moves from the fifth to the first floor in the manner previously discussed.

Closure of the break contacts **50-1** (FIG. 4) completed an energizing circuit for the no car call relay **SCCO** when the non-interference relay **70T** timed out to close its break contacts **70T3**. Such energization resulted in the operation of the contacts **SCCO1** through **SCCO8** (FIG. 2) to establish an artificial car call for the car A for the sixth floor, to prevent the registration of car A car calls for the third through sixth floors, and to prevent the registration of a car A car call for the second floor when the car is conditioned for up travel. Subsequent to the arrival of the car A at the first floor, the car moves to and from the sixth floor in response to the artificial car call therefor to provide special service as set forth above. Thus, it will be appreciated that before an elevator car initially can provide special service for an assigned floor, all car calls which may be registered for such car must be answered.

During an assigned period of special service operation, in this instance from 11:15 a.m. to 11:25 a.m. for the sixth floor, as long as a heavily-loaded car leaves its assigned floor before its associated dispatching timing relay times out (for example, the relay **SLHT** (FIG. 4) for the car A), such car will operate as previously discussed for the elevator car A. Assume, however, that the car A is located at the sixth floor in the period during

which it is assigned thereto and that its dispatching timing relay **SLHT** times out before the car is loaded sufficiently to open the load switch **WH**. (It will be recalled that the relay **SLHT** has a 15 second time delay in dropout after the make contacts **70T5** open upon dropout of the non-interference relay **70T**.) Closure of the break contacts **SLHT1** results in energization of the dispatching relay **80N** through the now closed make contacts **J4**. The make contacts **80N1** (FIG. 1) thereby close to energize the down switch **D** and the running relay **M** after the doors associated with the elevator car A close. Thus, the car is started from the sixth floor for travel to the second and first floors despite the fact that the car was not heavily loaded at the sixth floor. Since sufficient load was not present in the car at the sixth floor to open the load switch **WH** (FIG. 4) to drop out the load relay **W5T** in series therewith, the break contacts **W5T1** remained open to prevent energization therethrough of the auxiliary load relay **SWR**.

If it also be assumed that each of the cars B and C is not loaded sufficiently to drop out its associated load relay before its dispatching timing relay drops out, such cars likewise will be started from the sixth floor for travel to the second and first floors by operation of the break contacts **BSLHT1** and similar contacts for the car C. In addition, their respective associated auxiliary load relays **BSWR** and **CSWR** (not shown) will remain dropped out.

Turning now to FIG. 5, it will be observed that the timing relay **CTA** remains connected to the bus **L1** and that the capacitor **CA1** continues to charge through the make contacts **CNR2** and the break contacts **SWR1**, **BSWR1** and **CSWR1** as long as the auxiliary load relays **SWR**, **BSWR** and **CSWR** for the cars A, B and C, respectively, remain dropped out. Furthermore, during this period the make contacts **SWR2**, **BSWR2** and **CSWR2** and the break contacts **CNR3** all remain open to interrupt the discharge circuit for the capacitor **CA1**. (It will be appreciated that as long as a heavily-loaded assigned car leaves the sixth floor before the capacitor **CA1** charges sufficiently to fire the tube **TU1** to energize the timing relay **CTA**, the auxiliary load relay associated with such car will pick up to reset the timing circuit, i.e., to initiate a new timing operation of the timing relay.) Assuming that all three auxiliary load relays continue to remain dropped out without interruption for a period of at least 90 seconds from the last previous dropout thereof, at the expiration of such period, the capacitor **CA1** charges sufficiently to fire the tube **TU1** in the manner previously described. Such firing results in the energization of the relay **CTA** through the following circuit:

L1, CNR2, SWR1, BSWR1, CSWR1, CTA, 310, 311, L2A

Closure of the make contacts **CTA1** results in energization of the transfer relay **CTX** through the make contacts **SWRX1**, and this relay closes its make contacts **CTX5** to establish a holding circuit therefor. (Note that the transfer relay **CTX** initially cannot be energized unless at least one heavily-loaded elevator car previously has left the sixth floor. This follows from the fact that initial energization of the master load relay **SWRX** to close the make contacts **SWRX1** is effected through a set of make contacts of the auxiliary load relay associated with such car, for example, the contacts **SWR3** for the car A, as heretofore explained.) Closure of the make contacts **CTA2** establishes a holding circuit around the tube **TU1** through the resistor **R7**. Inasmuch as the contacts **CTA2** and the resistor **R7** now shunt the plate and cathode electrodes of the tube **TU1**, the discharge between such electrodes terminates.

Opening of the break contacts **CTX6** interrupts the energizing circuit for the master car assigning relay **CNR** and the master load relay **SWRX**. Opening of the make contacts **SWRX1** has no immediate effect on operation for the reason that the relay **CTX** is maintained energized through its holding contacts **CTX5**. Opening of the hold-

ing contacts SWRX2 prevents subsequent energization therethrough of the relay SWRX.

In dropping out, the master car assigning relay CNR opens its make contacts CNR1 to drop out the car assigning relays SLHOB, BSLHOB and CSLHOB for the elevator cars A, B and C, respectively. Opening of the make contacts CNR2 interrupts the charging circuit for the capacitor CA1 and the energizing circuit for the timing relay CTA, but such deenergization has no immediate effect on operation. Closure of the break contacts CNR3 completes the discharge circuit for the capacitor CA1, and the capacitor thus discharges through the resistor R5.

Returning now to the car assigning relays SLHOB, BSLHOB and CSLHOB, the dropout of such relays as a result of the opening of the make contacts CNR1 now will be discussed, with specific reference to the contacts of the relay SLHOB for the car A. The following comments, however, also apply to the contacts of the relays BSLHOB and CSLHOB for the cars B and C, respectively.

In dropping out, the relay SLHOB opens its make contacts SLHOB1 (FIG. 1) to prevent subsequent energization therethrough of the reversing relay J. Closure of the break contacts SLHOB2 (FIG. 3) permits the subsequent energization therethrough of the car call stopping relay S for the car A in response to registered up and down floor calls for all six floors served by the elevator system, while closure of the break contacts SLHOB3 permits the cancellation of such calls if they are answered by the car A. Opening of the make contacts SLHOB4 through SLHOB7 (FIG. 4) permits the functioning of the break contacts above those for the first floor of the up and down floor call registering relays in the call circuit 30. Opening of the break contacts SLHOB8 interrupts the energizing circuits for the no car call relay SCCO, the assigned floor relay NOX, the dispatching timing relay SLHT and the auxiliary load relay SWR. Opening of the make contacts SLHOB9 results in deenergization of the no-up-service signs 101. Dropout of the car assigning relays SLHOB, BSLHOB and CSLHOB, therefore, has resulted in transfer of the cars A, B and C, respectively, from special service operation to off-peak operation.

Turning now to FIG. 3, pickup of the transfer relay CTX to return the cars A, B and C to off-peak operation resulted in the opening of its break contacts CTX1 through CTX4. Opening of the contacts CTX2, CTX3 and CTX4 has no immediate effect on operation, since the break contacts NO4-2, NO2-3 and NO3-2 of the floor selection relays NO4, NO2 and NO3 respectively in parallel therewith remain closed at this time. Opening of the contacts CTX1, however, results in the opening of the floor call cancelling circuit associated with the contact segment /6 for the sixth floor, since it will be recalled that the break contacts NO1-3 in parallel with the contacts CTX1 also are open at this time.

Assume now that the following conditions occur: The car A is located at the sixth floor, the cars B, C and D are located at the first floor, and the non-interference relay 70T has timed out to open its make contacts 70T2 in series with the brush hh. It will be observed, therefore, that both of the down floor call cancelling circuits for the car A now are in open condition. Assume further that a larger number of people than can be handled by the car A alone suddenly desire elevator service in the down direction from the sixth floor, i.e., that such rush of traffic occurs later than expected, bearing in mind that all four cars of the elevator system now are conditioned for off-peak operation.

Inasmuch as the make contacts 70T2 have opened, even though the car A has not yet left the sixth floor a prospective down passenger who is unable to enter the car because it is loaded may register a down floor call for the sixth floor by pressing the down floor call push-button 6D; that is, since the two down floor call cancelling circuits now are ineffective, a down floor call may be registered for the sixth floor although one of the ele-

vator cars, in this case the car A, still is located at the sixth floor. The registration of such call results in the subsequent travel of the cars B, C and D to the sixth floor to provide down service therefor by a sequence which will be apparent from the preceding discussion. Thus, although the cars A, B and C effectively have been transferred back to off-peak operation, provision is made for expediting service in the event that there is a sudden rush of passengers desiring transportation in the down direction from the previously assigned floor, in this instance the sixth floor, between the time of such transfer and the beginning of the next assigned period of special service operation.

In summarizing the features of special service operation as thus far described, particular note may be made of the following points: An assigned car leaves its assigned floor in the down direction of travel in response to the presence of a predetermined load in such car. If an assigned car does not depart its assigned floor so loaded within a predetermined time after arriving at such floor (in the present system 15 seconds after the dropout of its non-interference relay), it is nevertheless started from its assigned floor in the down direction of travel. If no assigned car leaves the assigned floor with such predetermined load within a predetermined time after the leaving of the last previously loaded assigned car from such floor (in the present system 90 seconds), all assigned cars effectively are transferred back to off-peak operation for the remainder of the associated assigned period of special service operation. As long as an assigned car leaves the assigned floor with a predetermined load before the expiration of the last-named predetermined time, however, all assigned cars continue to return to their assigned floor to provide special service therefor. If the assigned cars effectively are transferred from special service operation back to off-peak operation before the expiration of the associated assigned period, provision is made for expediting a sudden rush of down traffic from the previously assigned floor by permitting the registration of a down floor call for such floor for the remainder of such assigned period although at the time of such registration an elevator car is located at that floor.

Several additional features of operation may be noted at this time. Each assigned car answers all car calls registered therefor at the beginning of an assigned period of special service operation before proceeding to the assigned floor to provide special service therefor. An assigned car bypasses all registered up and down floor calls as long as it is assigned to provide special service operation, and such car during such assignment responds to car calls only for predetermined floors (in the illustrated embodiment of the invention, the second or cafeteria floor and the lower terminal floor).

Although in the preceding example it was assumed that all cars were located at the first floor at the beginning of the assigned period of special service operation, it will be apparent from the foregoing discussion that if an assigned car is located above the lower terminal floor conditioned for down travel at such beginning, it will travel down to the lower terminal floor, answering all of its registered car calls on the way down, become conditioned for up travel at the lower terminal floor and subsequently proceed to the assigned floor to provide special service therefor.

It also will be observed that during the entire first assigned period of special service operation the elevator car D continuously remains conditioned for off-peak operation, that is, the car D may at all times answer all car calls registered therefor and all registered floor calls. Although during each period of special service operation it is to be expected that there will be relatively little or no demand for elevator service for floors other than the associated assigned floor, in the event that there is

such demand at least one car remains conditioned to respond thereto.

At 11:25 a.m. the floor selection relay NO2 is energized by a sequence which will be apparent from the preceding discussion of the apparatus of FIG. 5. It will be recalled that before the notching timing relay CLT times out to open its make contacts CLT1, the floor selection relays NO1 and NO2 simultaneously are energized and picked up. Thus, if the transfer relay CTX was picked up to transfer the cars A, B and C back to off-peak operation during the remainder of the first assigned period of special service operation, the concurrent open condition of the break contacts NO1-6 and NO2-6 effects interruption of the holding circuit for the relay CTX and this relay drops out. Dropout of the relay CTX together with the subsequent dropout of the floor selection relay NO1 results in the closure of the break contacts CTX1 and NO1-3 (FIG. 3) to restore the floor call cancelling circuits for the sixth floor to normal operation.

Opening of the break contacts NO2-8 (FIG. 5) prevents energization therethrough of the car assigning relay CSLHOB for the elevator car C. However, the car assigning relays SLHOB and BSLHOB for the cars A and B, respectively, are energized through the now closed make contacts CNR1.

Referring now to FIG. 2, when the floor selection relay NO1 drops out, the make contacts NO1-1 and NO1-2 and similar contacts for the car C open to "cancel" the artificial car calls for the sixth floor for the cars A, B and C. Closure of the make contacts NO2-1 and NO2-2 results in the registration of artificial car calls for the fourth floor for the cars A and B through the make contacts SCCO4 and BSCCO5, respectively, when the no car call relays SCCO and BSCCO are energized as previously described for the first assigned period of special service operation. Operation of the remaining relays of the system and their associated contacts will be apparent from the foregoing discussion. Thus, during the second assigned period of special service operation (11:25 a.m. to 11:31 a.m.), the cars A and B are assigned to the fourth floor to provide special service therefor. While these cars are assigned to the fourth floor, their operation essentially is the same as that described for the cars assigned to the sixth floor during the previous period, as will be apparent by inspection of the drawings. For clarification, it may be added that the cars A and B during up travel thereof stop and reverse their direction of travel at the fourth floor as long as they remain assigned to such floor during the second period. Furthermore, during the second period, the cars C and D, since they are unassigned, remain conditioned for off-peak operation.

In order more fully to describe the operation of the no car call relays, let it be assumed that at the start of the second period of special service operation the car A is located below the third floor conditioned for up travel and that car calls are registered for the car A for the third and fifth floors. As a result thereof, the make contacts 3CR2 and 5CR2 (FIG. 2) are closed to energize the car call relay 50 through the make contacts SLHO1. Thus, the open break contacts 50-1 (FIG. 4) prevent energization therethrough of the no car call relay SCCO. Since the make contacts SCCO4 (FIG. 2) now are open, there is no registration of an artificial car call for the fourth floor for the car A.

The car A, while traveling up, answers the registered car call for the third floor and thence proceeds to answer the registered car call for the fifth floor. As the elevator car nears the fifth floor, the brush kk (FIG. 4) engages the contact segment k5 to complete the following energizing circuit for the call above relay 78U:

L1, 6CR3, SLHOB4 in parallel with 6DR2
and

SUR2 in series, k5, kk, W8, 78U, L2

As a result of its energization, the call above relay 78U 75

closes its make contacts 78U1 (FIG. 1) to complete with the contacts SLHOB1 and X3 an energizing circuit for the reversing relay J.

The reversing relay opens its break contacts J1. Inasmuch as the make contacts M2 of the running relay open as the car comes to a stop at the fifth floor, it follows that the up preference relay W is deenergized as the elevator car stops. The deenergized up preference relay closes its break contacts W2 to complete an energizing circuit for the down preference relay X. Since the down preference relay now is energized and the up preference relay W is deenergized, the elevator car A is conditioned for subsequent travel in the down direction. The make contacts J2 close to establish a holding circuit for the relay J through the now closed break contacts M4. The break contacts J3 (FIG. 4) open to prevent subsequent energization therethrough of the dispatching relay 80N, while the make contacts J4 close to energize the dispatching relay through the closed break contacts NOX3 of the assigned floor relay NOX.

Inasmuch as the car A has answered its previously registered car calls for the third and fifth floors, the make contacts 3CR2 and 5CR2 (FIG. 2) now are open, and the car call relay 50, therefore, is dropped out. Upon expiration of the non-interference time, the relay 70T (FIG. 1) drops out to close its break contacts 70T3 (FIG. 4) to complete with the now closed break contacts 50-1 and make contacts SLHOB8 an energizing circuit for the no car call relay SCCO.

The make contacts SCCO9 close to establish a holding circuit for the relay SCCO. The break contacts SCCO10 open to prevent subsequent energization therethrough of the dispatching relay 80N. The make contacts SCCO11 close, but such closure has no immediate effect on operation for the reason that the break contacts J3 in series therewith now are open.

Turning now to FIG. 2, closure of the make contacts SCCO1 and SCCO6 has no immediate effect on operation, since the contacts of the floor selection relays respectively in series therewith are open at this time. Opening of the break contacts SCCO2, SCCO3, SCCO5 and SCCO7 renders the car call registering circuits for the sixth, fifth, fourth and third floors ineffective to stop the car A at such floors in response to the pressing of the car call pushbuttons 6c, 5c, 4c and 3c, respectively. Opening of the break contacts SCCO8 has the same effect if the car call pushbutton 2c for the second floor is pressed when the break contacts W3 are open, i.e., when the car A is conditioned for up travel. The make contacts SCCO4 close to register through the now closed make contacts NO2-1 an artificial car call for the fourth floor.

In dropping out, the non-interference relay 70T (FIG. 1) closed its break contacts 70T1. Inasmuch as the make contacts 80N1 are closed, as a result of the previously discussed energization of the dispatching relay, the subsequent closing of all of the doors associated with the elevator car A results in closure of the make contacts DR1 to energize the down switch D and the running relay M. The car A thus accelerates to full speed in the down direction.

As the car approaches the fourth floor, the brush aa (FIG. 2) engages the contact segment a4 to establish the following energizing circuit for the car call stopping relay T:

65 L1, SCCO4, NO2-1, a4, aa, X4, T, M5, L2

In picking up, the car call stopping relay closes its make contacts T1 (FIG. 1) subsequently to stop the car A at the fourth floor by a sequence which will be understood from the foregoing discussion.

The car A now is conditioned to provide special service for the fourth floor in a manner which will be clear from the discussion of such service for the sixth floor during the preceding period of special service operation.

From the preceding description of the operation of

the no car call relay SCCO, it will be apparent that if a car call or calls are registered for an assigned elevator car at the beginning of an assigned period of special service operation which the car may answer in the direction of travel for which it is conditioned at such beginning, the car first will answer such car calls, reverse its direction of travel after answering the farthest of such car calls in its direction of travel, and thereafter proceed to the assigned floor to provide special service therefor.

At 11:31 a.m. the floor selection relay NO3 (FIG. 5) is energized and the floor selection relay NO2 subsequently is deenergized by a sequence which will be apparent from the preceding discussion of FIG. 5. Opening of the break contacts NO3-6 and NO3-7 prevents energization therethrough of the car assigning relays BSLHOB and CSLHOB for the elevator cars B and C, respectively. It will be observed, however, that the car assigning relay SLHOB is energized through the break contacts NO4-6 and the make contacts CNR1 to condition the car A for special service operation. The make contacts NO2-1 and NO2-2 (FIG. 2), as a result of the dropout of the floor selection relay NO2, open to cancel the artificial car calls for the fourth floor for the cars A and B. Assuming that the no car call relay SCCO (FIG. 4) is energized, the make contacts NO3-1 (FIG. 2) close to register with the make contacts SCCO6 an artificial car call for the third floor. Thus, during the third assigned period of special service operation (11:31 a.m. to 11:35 a.m.), the car A provides special service for the third floor in a manner similar to that heretofore described for the sixth and fourth floors, while the cars B, C and D remain conditioned for off-peak operation.

At 11:35 a.m. the floor selection relay NO4 (FIG. 5) is energized, while the floor selection relay NO3 shortly thereafter is deenergized. Opening of the break contacts NO4-6 prevents energization therethrough of the car assigning relay SLHOB for the car A. Closure of the break contacts NO3-6 and NO3-7, however, results in energization of the car assigning relays BSLHOB and CSLHOB for the cars B and C, respectively.

By reference to FIG. 2, it will be observed that the make contacts NO3-1 now are open to cancel the artificial car call for the car A for the third floor. Closure of the make contacts BSCCO3 and NO4-1 and similar contacts for the car C establishes artificial car calls for the fifth floor for the cars B and C, respectively. Thus, during the fourth assigned period of special service operation (11:35 a.m. to 11:42 a.m.), the cars B and C provide special service for the fifth floor in a manner similar to that heretofore described for the sixth, fourth and third floors, while the cars A and D remain conditioned for off-peak operation during the entire fourth assigned period.

At 11:42 a.m. the floor selection relay NO4 (FIG. 5) is deenergized. Since the notching relay 61 at this time is picked up to open its break contacts 61-1, opening of the break contacts NO4-4 interrupts the holding circuit for the special service master relay SLHO, and this relay is deenergized. In dropping out, the relay SLHO effects the termination of special service operation for the entire elevator system by opening its make contacts SLHO4. All of the elevator cars, therefore, become conditioned for off-peak operation and remain so conditioned until the start of the next period of special service operation at 11:15 a.m. on the following day, provided the manually-operable switch 103 then is in closed condition.

In summarizing the sequence of special service operation as herein set forth for the present elevator system, it will be noted that during the first period thereof three cars (A, B and C) are assigned to the sixth floor for ten minutes (11:15 a.m. to 11:25 a.m.), while car D remains conditioned for off-peak operation; during the second period, two cars (A and B) are assigned to the fourth floor for six minutes (11:25 a.m. to 11:31 a.m.), while cars C and D remain conditioned for off-peak opera-

tion; during the third period one car (A) is assigned to the third floor for four minutes (11:31 a.m. to 11:35 a.m.), while three cars (B, C and D) remain conditioned for off-peak operation; and during the fourth period, two cars (B and C) are assigned to the fifth floor for seven minutes (11:35 a.m. to 11:42 a.m.), while the cars A and B remain conditioned for off-peak operation.

Since the car D in the illustrated embodiment of the invention continuously remains conditioned for off-peak operation, it will be appreciated that apparatus associated only with special service operation, for example apparatus similar to that illustrated in the lower half of FIG. 4 for the cars A and B, need not be provided for the car D. In this connection, it may be noted that a dispatching relay corresponding to the relays 80N and B80N for the cars A and B, respectively, is not required for the car D, and that break contacts of the car D call relay may be substituted for dispatching relay make contacts in that car's running relay and up and down switch circuits (refer to the circuits of the running relays and the up and down switches for the cars A and B in FIG. 1). Furthermore, a reversing relay and apparatus associated therewith need not be furnished for the car D, since in the present system a car conditioned for off-peak operation reverses its direction of travel only at the upper and lower terminal floors.

It will be appreciated that the number of elevator cars assigned to each floor and the period of time during which such cars are assigned to such floor for special service operation depend upon several factors, each of which may vary from building to building. Among these factors are the number of floors in the particular building, the number of cars in the elevator system serving the building, the total population of the building, the distribution of such population among the floors, the traffic expected at each of the floors during its assigned period and the total allowable time which may be allotted for special service operation. From the discussion of the present system, it also will be apparent that the desired sequence of special service operation for different buildings may be furnished by modifying the operation of the one-half hour clock and, if necessary, by adding a one-hour clock with appropriate contacts to operate in cooperation with the one-half hour clock. Additionally, the remaining apparatus associated with special service operation likewise may be modified to provide the desired service.

While the invention has been described with reference to certain specific embodiments thereof, numerous modifications falling within the spirit and scope of the invention are possible.

We claim as our invention:

1. In an elevator system, a structure having a plurality of floors, an elevator car for transporting load to and from said floors, means mounting the elevator car for movement relative to the structure to serve the floors, control means for operating the elevator car in a first direction and in a second direction opposite to said first direction and for stopping the elevator car at desired floors of the structure, first means automatically effective in response to occurrence of a predetermined condition for modifying operation of the elevator car to condition the elevator car to provide service in only a predetermined one of said directions from each of successive different ones of said floors in accordance with a predetermined sequence, each of said successive floors respectively being served in the last-named manner on a plurality of successive trips by the elevator car, means responsive to a traffic condition for determining the total number of such successive trips, second means coacting with said first means for stopping the elevator car at each of said successive floors when traveling toward such floor in the other of said two directions, third means coacting with said first and second means for reversing the elevator car for subsequent travel from the last-named

floor in said predetermined direction on each of the plurality of successive trips associated with such floor, and means responsive to a predetermined traffic condition for starting the elevator car from said last-named floor in said predetermined direction.

2. In an elevator system, a structure having a plurality of floors, an elevator car for transporting load to and from said floors, means mounting the elevator car for movement relative to the structure to serve the floors, control means for operating the elevator car in a first direction and in a second direction opposite to said first direction and for stopping the elevator car at desired floors of the structure, first means automatically effective in response to occurrence of a predetermined condition for modifying operation of the elevator car to condition the elevator car to provide service in only a predetermined one of said directions from each of successive different ones of said floors in accordance with a predetermined sequence, each of said successive floors respectively being served in the last-named manner on a plurality of successive trips by the elevator car, means responsive to a traffic condition for determining the total number of such successive trips, second means coacting with said first means for stopping the elevator car at each of said successive floors when traveling toward such floor in the other of said two directions, third means coacting with said first and second means for reversing the elevator car for subsequent travel from the last-named floor in said predetermined direction on each of the plurality of successive trips associated with such floor, and means for starting the elevator car from said last-named floor in said predetermined direction in response to a first or a second predetermined traffic condition, whichever occurs first.

3. In an elevator system, a structure having a plurality of floors, an elevator car for transporting load to and from said floors, means mounting the elevator car for movement relative to the structure to serve the floors, control means for operating the elevator car in a first direction and in a second direction opposite to said first direction and for stopping the elevator car at desired floors of the structure, first means automatically effective in response to occurrence of a predetermined condition for modifying operation of the elevator car to condition the elevator car to provide service in only a predetermined one of said directions from each of successive different ones of said floors in accordance with a predetermined sequence, each of said successive floors respectively being served in the last-named manner on a plurality of successive trips by the elevator car, second means coacting with said first means for stopping the elevator car at each of said successive floors when traveling toward such floor in the other of said two directions, third means coacting with said first and second means for reversing the elevator car for subsequent travel from the last-named floor in said predetermined direction on each of the plurality of successive trips associated with such floor, means responsive to a first traffic condition for starting the elevator car from said last-named floor in said predetermined direction after the expiration of a first predetermined time following the stopping of the elevator car at said last-named floor, and means responsive to a second traffic condition for starting the elevator car from said last-named floor in said predetermined direction after the expiration of a second predetermined time following the stopping of the elevator car at said last-named floor.

4. In an elevator system, a structure having a plurality of floors, an elevator car for transporting load to and from said floors, means mounting the elevator car for movement relative to the structure to serve the floors, control means for operating the elevator car in a first direction and in a second direction opposite to said first direction and for stopping the elevator car at desired floors of the structure,

- first means automatically effective in response to occurrence of a predetermined condition for modifying operation of the elevator car to condition the elevator car to provide service in only a predetermined one of said directions from each of successive different ones of said floors in accordance with a predetermined sequence, each of said successive floors respectively being served in the last-named manner on a plurality of successive trips by the elevator car, second means coacting with said first means for stopping the elevator car at each of said successive floors when traveling toward such floor in the other of said two directions, third means coacting with said first and second means for reversing the elevator car for subsequent travel from the last-named floor in said predetermined direction on each of the plurality of successive trips associated with such floor, means responsive to the presence of a predetermined load in the elevator car for starting the elevator car from said last-named floor in said predetermined direction, and means responsive to the expiration of a predetermined time following the stopping of the elevator car at said last-named floor for starting the elevator car from said last-named floor in said predetermined direction although said predetermined load is not present in the elevator car.
5. In an elevator system, a structure having a plurality of floors including a first terminal floor, a second terminal floor and a plurality of floors intermediate the terminal floors, an elevator car for transporting load to and from said floors, means mounting the elevator car for movement relative to the structure to serve the floors, and control means for controlling the elevator car for movement between the terminal floors in a first direction and in a second direction opposite to said first direction and for stopping the elevator car at desired floors of the structure to provide a first mode of elevator service for said floors, said control means including first means automatically effective in response to occurrence of a first predetermined condition for modifying the movement and the stopping of the elevator car to provide a second mode of elevator service for said floors, and second means responsive to the occurrence of a predetermined traffic condition at a predetermined one of said floors when the elevator car is conditioned to provide said second mode of service for rendering said first means ineffective further to condition the elevator car to provide said second mode of service at least until the occurrence of a second predetermined condition and for transferring the elevator car from said second mode to said first mode of service.
6. In an elevator system, a structure having a plurality of floors including a first terminal floor, a second terminal floor and a plurality of floors intermediate the terminal floors, an elevator car for transporting load to and from said floors, means mounting the elevator car for movement relative to the structure to serve the floors, and control means for moving and for stopping the elevator car, said control means including first means operable for moving the elevator car between said terminal floors in a first direction and in a second direction opposite to said first direction and for stopping the elevator car at desired floors of the structure, second means automatically effective at a predetermined time for assigning the elevator car to each of a plurality of predetermined different ones of said floors in accordance with a predetermined sequence, third means coacting with said second means for modifying operation of said first means to condition the elevator car to provide service from each of said predetermined floors on a plurality of successive trips by the elevator car in only a predetermined one of said directions in response to at least a first predetermined traffic condition, and fourth means responsive to the occurrence of a second predetermined traffic condition for rendering said third means ineffective so to modify operation of said first means until the elevator car is assigned to the next sequential one of said predetermined floors.
7. In an elevator system, a structure having a plurality

of floors including a first terminal floor, a second terminal floor and a plurality of floors intermediate the terminal floors, an elevator car for transporting load to and from said floors, means mounting the elevator car for movement relative to the structure to serve the floors, and control means for moving and for stopping the elevator car, said control means including first means operable for moving the elevator car between said terminal floors in a first direction and in a second direction opposite to said first direction and for stopping the elevator car at desired floors of the structure, timing mechanism for measuring successive predetermined intervals of time, assigning means and reversing means responsive to operation of said timing mechanism for establishing a modified mode of operation of the elevator car during each of said intervals of time, said assigning means being effective for stopping the elevator car when traveling in a first of said two directions on each of a plurality of successive trips at a predetermined different one of said floors respectively during each of said intervals in accordance with a predetermined sequence, said reversing means being operable in cooperation with said assigning means for reversing the elevator car for subsequent travel in the second of said two directions from the last-named floor, means responsive to at least a first predetermined traffic condition at said last-named floor for starting the elevator car therefrom in said second direction, and means responsive to the occurrence of a second predetermined traffic condition at said last-named floor for rendering said assigning means and said reversing means ineffective so to modify operation of the elevator car between said occurrence and the beginning of the next successive one of said intervals of time.

8. In an elevator system, a structure having a plurality of floors including a first terminal floor, a second terminal floor and a plurality of floors intermediate the terminal floors, an elevator car for transporting load to and from said floors, means mounting the elevator car for movement relative to the structure to serve the floors, and control means for moving and for stopping the elevator car, said control means including first means operable for moving the elevator car between terminal floors in a first direction and in a second direction opposite to said first direction and for stopping the elevator car at desired floors of the structure, timing mechanism for measuring successive predetermined intervals of time, assigning means and reversing means responsive to operation of said timing mechanism for establishing a modified mode of operation of the elevator car during each of said intervals of time, said assigning means being effective for stopping the elevator car when traveling in a first of said two directions on each of a plurality of successive trips at a predetermined different one of said floors respectively during each of said intervals in accordance with a predetermined sequence, said reversing means being operable in cooperation with said assigning means for reversing the elevator car for subsequent travel in the second of said two directions from the last-named floor, means responsive to the presence of a predetermined load in the elevator car for starting the elevator car from said last-named floor in said second direction, means responsive to the expiration of a first predetermined time following the stopping of the elevator car at said last-named floor for starting the elevator car therefrom in said second direction although said predetermined load is not present in the elevator car, and means responsive to failure of the elevator car to start from said last-named floor in said second direction in response to said predetermined load after the termination of a second predetermined time longer than said first predetermined time following the last previous start of the elevator car from said last-named floor in response to said predetermined load for rendering said assigning means and said reversing means ineffective so to modify operation of the elevator car between the occurrence of said termination and the beginning of the next successive one of said intervals of time.

9. In an elevator system, a structure having a plurality of floors including a first terminal floor, a second terminal floor and a plurality of floors intermediate the terminal floors, an elevator car for transporting load to and from said floors, means mounting the elevator car for movement relative to the structure to serve the floors, and control means for moving the elevator car and for stopping the elevator car at desired floors of the structure, said control means comprising first call means operable from each of a plurality of the floors for registering calls for elevator service toward the second terminal floor, second call means operable from each of a plurality of the floors for registering calls for elevator service toward the first terminal floor, third call means operable for registering calls for elevator service for floors desired for load within the elevator car, first means for controlling the elevator car for movement between the terminal floors and for stopping the elevator car at each floor for which a call for service is registered by said first, second or third call means to provide a first mode of elevator service for said floors, second means automatically effective at a predetermined time for assigning the elevator car to each of a plurality of predetermined different ones of said floors in accordance with a predetermined sequence, third means coacting with said second means for modifying operation of said first means to condition the elevator car to provide service from each of said predetermined floors on a plurality of successive trips by the elevator car in only a predetermined one of said directions in response to at least a first predetermined traffic condition, fourth means responsive to said conditioning by said third means for rendering said first means ineffective for stopping the elevator car at floors for which calls are registered by said first or second call means, and means responsive to the occurrence of a second predetermined traffic condition for rendering said third and fourth means ineffective so to modify operation of said first means until the elevator car is assigned to the next sequential one of said predetermined floors.

10. In an elevator system, a structure having a plurality of floors including a first terminal floor, a second terminal floor and a plurality of floors intermediate the terminal floors, an elevator car for transporting load to and from said floors, means mounting the elevator car for movement relative to the structure to serve the floors, and control means for moving the elevator car and for stopping the elevator car at desired floors of the structure, said control means comprising first call means operable from the first terminal floor and from each of the intermediate floors for registering calls for elevator service toward the second terminal floor, second call means operable from the second terminal floor and from each of the intermediate floors for registering calls for elevator service toward the first terminal floor, car call means operable for registering a call for each of the floors desired for load within the elevator car, first means operable for moving the elevator car between terminal floors in a first direction and in a second direction opposite to said first direction and for stopping the elevator car at each floor approached by the elevator car in response to a call for service registered by said first or second call means or by said car call means for the floor being approached by the elevator car which may be served by approaching elevator car, timing mechanism for measuring successive predetermined intervals of time, assigning means and reversing means responsive to operation of said timing mechanism for establishing a modified mode of operation of the elevator car during each of said intervals of time, said assigning means being effective for stopping the elevator car when traveling in a first of said two directions on each of a plurality of successive trips at a predetermined different one of said floors respectively during each of said intervals in accordance with a predetermined sequence, said reversing means being operable in cooperation with said assigning means for reversing the ele-

vator car for subsequent travel in the second of said two directions from the last-named floor, means responsive to at least a first predetermined traffic condition at said last-named floor for starting the elevator car therefrom in said second direction, by-passing means responsive to the establishment of said modified mode of operation by said assigning means and said reversing means for rendering said car call means for at least a part of the floors disposed in said second direction from said last-named floor and said first and second call means ineffective for stopping the elevator car, and means responsive to the occurrence of a second predetermined traffic condition at said last-named floor for rendering said assigning, reversing and by-passing means ineffective so to modify operation of the elevator car between said occurrence and the beginning of the next successive one of said intervals of time.

11. In an elevator system, a structure having a plurality of floors including a first terminal floor, a second terminal floor and a plurality of floors intermediate the terminal floors, an elevator car for transporting load to and from said floors, means mounting the elevator car for movement relative to the structure to serve the floors, and control means for moving the elevator car and for stopping the elevator car at desired floors of the structure, said control means comprising first call means operable from the first terminal floor and from each of the intermediate floors for registering calls for elevator service toward the second terminal floor, second call means operable from the second terminal floor and from each of the intermediate floors for registering calls for elevator service toward the first terminal floor, car call means operable for registering a call for each of the floors desired for load within the elevator car, first means operable for moving the elevator car between terminal floors in a first direction and in a second direction opposite to said first direction and for stopping the elevator car at each floor approached by the elevator car in response to a call for service registered by said first or second call means or by said car call means for the floor being approached by the elevator car which may be served by the approaching elevator car, timing mechanism for measuring successive predetermined intervals of time, assigning means and reversing means responsive to operation of said timing mechanism for establishing a modified mode of operation of the elevator car during each of said intervals of time, said assigning means being effective for stopping the elevator car when traveling in a first of said two directions on each of a plurality of successive trips at a predetermined different one of said floors respectively during each of said intervals in accordance with a predetermined sequence, said reversing means being operable in cooperation with said assigning means for reversing the elevator car for subsequent travel in the second of said two directions from the last-named floor, means responsive to the presence of a predetermined load in the elevator car for starting the elevator car from said last-named floor in said second direction, means responsive to the expiration of a first predetermined time following the stopping of the elevator car at said last-named floor for starting the elevator car therefrom in said second direction although said predetermined load is not present in the elevator car, bypassing means responsive to the establishment of said modified mode of operation by said assigning means and said reversing means for rendering said car call means for at least a predetermined part of the floors disposed in said second direction from said last-named floor and said first and second call means ineffective for stopping the elevator car, means responsive to failure of the elevator car to start from said last-named floor in said second direction in response to said predetermined load after the termination of a second predetermined time longer than said first predetermined time following the last previous start of the elevator car from said last-named floor in response to said predetermined load for render-

ing said assigning, reversing and by-passing means ineffective so to modify operation of the elevator car between the occurrence of said termination and the beginning of the next successive one of said intervals of time, and means responsive to the presence of a call registered by said car call means for rendering said assigning means and said reversing means ineffective for establishing said modified mode of operation of the elevator car.

12. In an elevator system for a structure having a plurality of floors including a first terminal floor, a second terminal floor and a plurality of floors intermediate the terminal floors, a plurality of elevator cars for transporting load to and from said floors, means mounting the elevator cars for movement relative to the structure to serve the floors, and control means for moving the elevator cars and for stopping the elevator cars at desired floors of the structure, said control means comprising first call means operable from each of a plurality of the floors for registering calls for elevator service toward the second terminal floor, second call means operable from each of a plurality of the floors for registering calls for elevator service toward the first terminal floor, third call means operable for registering calls for elevator service for floors desired for load within each of the elevator cars, first means for moving the elevator cars between the terminal floors and for stopping each of the elevator cars at each floor approached by the last-named elevator car for which a call is registered by said first, second or third call means for the last-named floor which may be served by such approaching elevator car to provide a first mode of elevator service for said floors, second means automatically effective at a predetermined time for assigning successive predetermined numbers of the elevator cars to successive respective predetermined different ones of said floors in accordance with a predetermined sequence, third means coacting with said second means for modifying operation of said first means to condition each of said assigned elevator cars to provide service from the associated one of said predetermined floors on a plurality of successive trips by the last-named elevator car in only a predetermined one of said directions in response to at least a first predetermined traffic condition, fourth means responsive to said conditioning by said third means for rendering said third call means for at least a predetermined part of the floors disposed in said predetermined direction from the last named floor and said first and second call means ineffective for stopping each assigned elevator car, and means responsive to the occurrence of a second predetermined traffic condition for rendering said third and fourth means ineffective so to modify operation of said first means until the next sequential predetermined number of elevator cars is assigned to the next sequential one of said predetermined floors.

13. In an elevator system for a structure having a plurality of floors including a first terminal floor, a second terminal floor and a plurality of floors intermediate the terminal floors, a plurality of elevator cars for transporting load to and from said floors, means mounting the elevator cars for movement relative to the structure to serve the floors, and control means for moving the elevator cars and for stopping the elevator cars at desired floors of the structure, said control means comprising first call means operable from the first terminal floor and from each of the intermediate floors for registering calls for elevator service toward the second terminal floor, second call means operable from the second terminal floor and from each of the intermediate floors for registering calls for elevator service toward the first terminal floor, car call means operable for registering a call for each of the floors desired for load within each of the elevator cars, first means operable for moving the elevator cars between the terminal floors in a first direction and in a second direction opposite to said first direction and for

stopping each of the elevator cars at each floor approached by the last-named elevator car for which a call is registered by said first or second call means or by said car call means for the last-named floor which may be served by such approaching elevator car, timing mechanism for measuring successive predetermined intervals of time, assigning means and reversing means responsive to operation of said timing mechanism for establishing a modified mode of operation of the elevator system during each of said intervals of time, said assigning means being effective for assigning successive predetermined numbers of the elevator cars to successive respective predetermined different assigned ones of the floors respectively during each of said intervals of time in accordance with a predetermined sequence and for stopping each assigned elevator car, when traveling in a first of said two directions on each of a plurality of successive trips, at its associated assigned floor, said reversing means being operable in cooperation with said assigning means for reversing each assigned elevator car for travel in the second of said two directions from its associated assigned floor after the stopping of such car at such floor in the last-named manner, means responsive to at least a first predetermined traffic condition at each assigned floor for starting an associated assigned elevator car therefrom in said second direction, by-passing means responsive to the establishment of said modified mode of operation by said assigning means and said reversing means for rendering said car call means for at least a predetermined part of the floors disposed in said second direction from the last named floor and said first and second call means ineffective for stopping each assigned elevator car, and means responsive to the occurrence of a second predetermined traffic condition at each assigned floor for rendering said assigning, reversing and by-passing means ineffective so to modify operation of the elevator system between said occurrence and the beginning of the next successive one of said intervals of time.

14. In an elevator system for a structure having a plurality of floors including a first terminal floor, a second terminal floor and a plurality of floors intermediate the terminal floors, a plurality of elevator cars for transporting load to and from said floors, means mounting the elevator cars for movement relative to the structure to serve the floors, and control means for moving the elevator cars and for stopping the elevator cars at desired floors of the structure, said control means comprising first call means operable from the first terminal floor and from each of the intermediate floors for registering calls for elevator service toward the second terminal floor, second call means operable from the second terminal floor and from each of the intermediate floors for registering calls for elevator service toward the first terminal floor, car call means operable for registering a call for each of the floors desired for load within each of the elevator cars, first means operable for moving the elevator cars between the terminal floors in a first direction and in a second direction opposite to said first direction

and for stopping each of the elevator cars at each floor approached by the last-named elevator car for which a call is registered by said first or second call means or by said car call means for the last-named floor which may be served by such approaching elevator car, timing mechanism for measuring successive predetermined intervals of time, assigning means and reversing means responsive to operation of said timing mechanism for establishing a modified mode of operation of the elevator system during each of said intervals of time, said assigning means being effective for assigning successive predetermined numbers of the elevator cars to successive respective predetermined different assigned ones of the floors respectively during each of said intervals of time in accordance with a predetermined sequence and for stopping each assigned elevator car, when traveling in a first of said two directions on each of a plurality of successive trips, at its associated assigned floor, said reversing means being operable in cooperation with said assigning means for reversing each assigned elevator car for travel in the second of said two directions from its associated assigned floor after the stopping of such car at such floor in the last-named manner, means responsive to the presence of a predetermined load in each assigned elevator car for starting such car from its associated assigned floor in said second direction, means responsive to the expiration of a first predetermined time following the stopping of each assigned elevator car at its associated assigned floor for starting such elevator car therefrom in said second direction although said predetermined load is not present therein, by-passing means responsive to the establishment of said modified mode of operation by said assigning means and said reversing means for rendering said car call means for at least a predetermined part of the floors disposed in said second direction from the last-named floor and said first and second call means ineffective for stopping each assigned elevator car, means responsive to failure of an assigned elevator car to start from its associated assigned floor in said second direction in response to said predetermined load after the termination of a second predetermined time longer than said first predetermined time following the last previous start of an assigned elevator car from the last-named assigned floor in response to said predetermined load for rendering said assigning, reversing and by-passing means ineffective so to modify operation of the elevator system between the occurrence of said termination and the beginning of the next successive one of said intervals of time, and means responsive to the presence of a call registered by said car call means for an elevator-car-to-be-assigned for rendering said assigning means and said reversing means ineffective for establishing said modified mode of operation for said elevator-car-to-be assigned, each of said successive predetermined numbers of elevator cars including not more than one less than said plurality of cars.
